UNITED STATES PATENT OFFICE.

JOHN SELLERS BANCROFT, OF PHILADELPHIA, PENNSYLVANIA, ASSIGNOR
TO THE LANSTON MONOTYPE MACHINE COMPANY, OF WASHINGTON,
DISTRICT OF COLUMBIA.

TYPE-CASTING AND COMPOSING MACHINE.

SPECIFICATION forming part of Letters Patent No. 625,998, dated May 30, 1899.

Application filed March 21, 1899. Serial No. 709,909. (No model.)

To all whom it may concern:

Be it known that I, JOHN SELLERS BANCROFT, a citizen of the United States, residing at Philadelphia, in the county of Philadelphia and State of Pennsylvania, have invented certain new and useful Improvements in Type-Casting and Composing Machines; and I do hereby declare the following to be a full, clear, and exact description of the same, reference being had to the accompanying drawings, forming a part of this specification, and to the figures of reference marked thereon.

The present invention relates to and constitutes an improvement upon the type-making and composing mechanism forming part of what is known as the "Lanston monotype system," wherein a previously-prepared record-strip is employed to control and govern the operations of an automatic type-casting machine in the production of justified lines of type and the assembling of such justified lines of type in column form ready for use.

In view of the somewhat complex character of the apparatus embodying these improvements, and as an aid in understanding the description of the several mechanisms and their relations one to another and to the machines as a whole, it is desirable that the general mode of operation of the Lanston monotype system should be understood, to which end a brief description of its salient features as embodied in the most highly developed form in which it has been introduced to the public prior to the present invention will be attempted.

The Lanston system makes use of a record-strip prepared by punching at regular intervals holes representing each character and space entering into the composition of the matter to be set up. At the end of each series of perforations representing a complete line there is formed one or more perforations representing the amount to be added to each space-type of normal width in order to cause the series of character-type and spaces to justify or just fill the line. These perforations occurring at the end of the line are known as the "justification-perforations." Another perforation succeeds the justifica-

tion-perforation and is known as the "galley-perforation." The next line in the composition is set up in the same manner—that is to say, characters and spaces in the order in which they occur are registered by perforations—the amount of justification—*i. e.*, the increase in the width of the normal space-types—is then registered, after which the galley-perforation is made, and so on to any extent. The perforated record-strip thus made is delivered to the type-making and composing mechanism in the reverse order of composition, so that in the procession of events the justification adjustments for the first line produced in the machine will first be effected, then the characters and spaces in inverse order of composition will be successively formed, and after the last character for the line is completed the justification devices will be returned to zero and the galley mechanism brought into action to transfer the completed line to the galley, after which the justification for the next line and the formation of the characters for said line will proceed as before.

The principal elements of the type-making and composing machine are the die-case and its centering and clamping mechanisms; the mold, with its adjustable mold-blade for varying the size of the mold-cavity to produce type-bodies of different widths; the normal adjusting mechanism for the mold-blade for determining its position to correspond with the normal widths of the several characters represented by the matrices; the abnormal or justifying mechanism for varying the position of the mold-blade as effected by the normal adjusting devices, so as to increase the dimensions of the mold as to width when certain selected type, such as the space-type, are to be produced; the metal-injecting mechanism; the galley mechanism, the latter containing devices for assembling the completed type into a line, carrying said line into position to be transferred to the galley, and transferring the line into the galley, and a pneumatic system through which the perforated record-strip exercises control over the several devices or mechanisms enumerated.

According to the plan or system upon which said machine is constructed a complete rotation of the driving-shaft is required for the making of a single type. The die-case, in which the series of matrices representing the characters are assembled, is given a compound motion in two directions for centering or bringing any selected matrix into position above the mold, said motions being performed with reference to a common starting-point or zero position. Hence a complete reciprocation of the die-case in two directions is required each time a type is produced, the selection of the character being determined by the degree of motion given the die-case, measured from the common zero or starting position, to which latter the die-case is returned after the formation of each type. This involved a considerable travel of the die-case, even when a limited number of matrices was employed, and when it was sought to materially increase the number of matrices in the die-case the increased weight and range of motion incident thereto seriously affected the speed of the machine. Time was also lost in setting the justification devices and in starting the galley mechanism. For the former there was a starting or zero position, to which the justification devices had to be returned at the completion of a line and with reference to which the adjustment was performed for the next succeeding line. Moreover, the setting of the justifying devices absorbed several otherwise useless rotations of the driving-shaft, and the starting of the galley mechanism also required a blank or unproductive rotation of said shaft. It will readily be perceived that the foregoing, among other minor features not here enumerated, constitute distinct limitations upon the speed capacity of the machine considered as a whole, and it is one of the special and important objects of the present invention to overcome or at least materially modify these restrictions and to not alone improve the mechanisms whereby the several operations are performed, but to materially increase the capacity of the machine, both as to number of available characters and speed of production. With this end in view a new die-centering system has been contrived whereby the zero or starting point for the die-case has been eliminated and the motions reduced to a minimum by causing it to move directly from one point of adjustment to the next without first returning to a common starting-point. By this means the range of motion and consequent number of characters may be increased without correspondingly increasing the speed of motion of the die-case, and the shock of arrest incident to increased weight of the die-case is avoided. A new system for effecting both the normal and the abnormal or justifying adjustments of the mold-blade has also been devised, in which the zero position is likewise eliminated, the mechanism simplified, and the adjustment effected almost instantaneously, the maximum degree being

produced by but two revolutions of the driving-shaft, whereas in the Lanston machine several revolutions were consumed for this purpose.

Instead of employing a separate perforation in the record-strip and consuming one complete revolution of the driving-shaft for setting the galley mechanism into action the galley-perforation is dispensed with and the justification-perforation utilized for the purpose.

The foregoing are some of the principal fundamental improvements embodied in the present machine, and in addition thereto there are numerous subordinate features pertaining to the construction, arrangement, and combinations of the several mechanisms, all as will hereinafter more fully appear.

In the accompanying drawings, representing the preferred, but not the only, embodiment of all the several improvements in an organized machine, Figure 1 is a perspective view looking toward the front left-hand corner of the machine. Fig. 2 is a top elevation or plan view. Fig. 3 is a front elevation. Fig. 4 is a side elevation looking toward right-hand side of the machine. Fig. 5 is a rear elevation. Fig. 108 is a detail showing the air-bar in longitudinal section. Fig. 109 is a longitudinal vertical section through the paper-feed mechanism. Fig. 110 is a detail view showing one of the spool-supports in section. Fig. 111 is a diagrammatic view showing a section of the perforated record-strip. Fig. 112 is a diagrammatic view showing the air passages or connections of the pneumatic system. Fig. 113 is a detail showing the arrangement of the driving-cams. Fig. 114 is a perspective view of the link-motion for operating the transfer blocks or wedges. Fig. 115 is a transverse section through the driving-shafts, showing the arrangement of the lever, the cams illustrated in this figure being those for the type-ejector. Fig. 116 is a detail view showing the manner of adjusting the bevel-gear on its driving-shaft. Figs. 117 to 122, inclusive, illustrate, approximately, the outlines of the

various sets of cams for actuating the devices.

Corresponding parts in the several figures bear the same numerals. 70

For convenience of description the various mechanisms which together constitute the organized machine represented in the drawings may be considered in groups or divisions, according to their special functions, as follows: the mold, the die or matrix case, the die-centering mechanism, the normal mold-adjusting mechanism, the abnormal adjusting or justifying mechanism, the metal-injecting mechanism, the galley mechanism, 80 (including the type-carrier, line-carrier, and line-transferrer,) the paper-feed, and the pneumatic system.

Generically considered, similar elemental features are to be found in the prior Lanston 85 machine upon which this is an improvement, but from which it differs in many respects, more especially in the construction, arrangement, and mode of operation of the actuating mechanisms. 90

The general arrangement of the principal elements is best seen in Figs. 1 to 8, inclusive.

The mold occupies a fixed position nearly central of the machine, and above it is arranged the die-case, which latter is mounted to reciprocate horizontally in two directions, so as to bring any one of its dies or matrices centrally above the mold. Above the die-case and in line with the mold is the centering and pressing plunger by means of which the selected matrix is accurately centered and held tightly upon the upper end of the mold. The metal-injecting devices are located to the left of the mold, the nozzle being carried beneath the top plate of the frame in line with the mold. The paper-feed is arranged above the left-hand rear corner of the machine. The die-centering and the normal adjusting and justifying mechanisms occupy 100 positions in rear and to the left of the mold. The main driving-shaft is mounted upon the left side of the frame, and in this connection it may be stated that the frame, which may be of any desired or approved form, has in the 105 present instance been especially contrived to receive and accommodate the various mechanisms constituting the organized machine, but inasmuch as its form is not essential it will hereinafter be referred to merely as the 110 "main frame," whether considered as an integral structure or as comprised of separable elements. 115

With this preliminary outline of the relative arrangement and location of the principal elements of the machine the detail description may be proceeded with. 125

The Mold.

The mold may be regarded as the center 130 of the entire system of type-forming devices, occupying, as it does, a fixed position about

and with reference to which the other mechanisms are grouped and adjusted for coöperative action. Acting in conjunction with a separable matrix or die-block and a metal-
5 injecting apparatus the mold gives shape and dimension to the bodies of all the type, character as well as space, to which end it is furnished with a movable member or wall capable of adjustment so as to vary the size of the
10 mold-cavity, and thus produce type-bodies of different widths, setwise. The construction and arrangement of this part of the apparatus will be best understood by reference to Figs. 7, 19, 20, 21, and 56.

15 Although fixedly secured in position on the top plate of the frame and made up of several distinct parts, the mold as a whole constitutes a complete structure which can readily be attached and detached not only
20 from the main frame, but also from the actuating devices controlling its movable elements. It is composed of two stationary members or blocks 1 2, forming the opposite side walls of the mold-cavity, and a cross-
25 blade 3, movable across the ends of said blocks 1 and 2 and forming a removable front wall to the mold-cavity. The rear wall of said cavity is formed by the mold-blade 4, guided by and having movement between the
30 proximate faces of the blocks 1 and 2 and constituting the adjustable wall of the mold, as well as the ejector for discharging the type therefrom and delivering them into the type-carrier. These parts are mounted and sup-
35 ported in a frame 5, comprising front and rear vertical walls, a vertical wall extending partly across one end and a bottom plate or support. Although this frame 5 might be formed in one piece, for convenience of manu-
40 facture it is composed of several parts firmly united, as clearly indicated in Figs. 19, 20, and 21. One special reason for this sectional construction is the desirability of employing hardened and true surfaces for preserving
45 the parts in proper relative position, more especially those parts which furnish the walls of the mold-cavity. Hence the blocks 1 and 2 instead of extending down to the bottom plate of the frame, as they well might, are
50 each mounted upon a filling-piece, which latter is somewhat narrower than the blocks, as seen in Fig. 20. The block 1 is fixed in position, and the opposite block 2 may in like manner be fixed; but it is preferred to per-
55 mit slight lateral play to block 2, so that it may accommodate itself to variations in the temperature not only of the parts themselves, but also of the mold-blade, which latter is movably sustained between the two blocks.
60 A tight joint should at all times be main-
tained between the mold-blade and the faces of blocks 1 and 2, and unless adequate pro-
vision is made to accommodate expansion and contraction due to variations in temperature
65 there will be danger of binding and serious interference with the movements of the mold-
blade. To provide against this, the movable

or adjustable block 2 is held in contact with the mold-blade by a spring 6, Fig. 21, inter-
posed between said block and the end wall 70 of the frame. A set-screw at one end and a clamping-screw at the side serve to properly locate block 2, while a plate or keeper 7, fit-
ting accurately in cross-grooves in the upper 75 face of both blocks 1 and 2 and secured to the former and to the frame, insures the aline-
ment and parallelism of the two blocks and furnishes the top guide for the mold-blade. These blocks 1 and 2 are each provided with independent passages in close proximity to 80 the mold-blade for the circulation of water or other cooling agents.

The adjusting means for limiting the forward motion of the mold-blade operate directly upon the latter instead of upon its ac-
tuating devices, thus eliminating irregularities in position incident to lost motion and 85 expansion. Said adjusting means are mounted upon the mold-frame and comprise the ad-
justable wedge 8, with set-screw 9, the former 90 passing through an opening in the mold-
blade and taking its bearing on frame 5.

It will readily be understood that in the production of articles such as type whose variations in size are measured by the one-thou-
sandth and ten-thousandth of an inch and 95 whose bodies must be rectangular, clean and free from fins the matter of temperature and its incidents—expansion and contraction—is a very material factor, and it is to counteract 100 or neutralize this disturbing element that the mold-blade, as well as its adjusting devices, are mounted directly upon the mold and pro-
vision made for supplying a circulation of liquid in the side blocks 1 and 2, where it will 105 contribute its beneficial action to the mold-
blade. The front block or cross-blade 3 is also preferably made separate from its base 10, to which it is rigidly attached by screws, some of the latter passing through a vertical 110 plate 11, applied to the outer face of the cross-
blade 3 and its base 10. Between the side vertical wall of the base and the cross-blade 3 is arranged an adjustable wear-plate 12, which is sustained in position by adjusting- 115 screws in the frame, as seen in Figs. 20 and 21.

The base 10 of the cross-blade is formed in two sections slightly wider than the cross-
blade itself and projecting beneath the blocks 1 and 2, Fig. 20, and said sections of the base 120 are separated by an interval forming a trans-
verse groove 13, in which fits and reciprocates the ejector 14, the latter straddling a cam-
track 15, fixed to the base of the mold. The end of groove 13, when in vertical alinement 125 with the space between blocks 1 and 2, forms the passage through which molten metal is injected into the mold-cavity, and the but-
ton or jet formed in this passage is discharged therefrom by the ejector 14 when the cross-
blade is moved to uncover the front of the 130 mold-cavity.

Directly beneath and in line with the mold-
cavity the bottom plate of the mold-frame is

cut away for the reception of the nozzle-plate 16. As is usual, this plate is furnished on its under side with a conical seat for the reception of the nozzle, together with a jet opening or orifice; but it differs from others in having this seat formed with thin bell-shape walls 17 and in having the supporting-plate slightly concaved on the under side. Two objects are accomplished by this arrangement. In the first place, the chilling of the metal in the nozzle is avoided by diminishing the mass of the metal with which it is brought into close contact when the cast is made, and, in the second place, the warping and splitting of the nozzle-plate, resulting from the contact with the hot nozzle, is prevented.

The rear portion of the mold-blade is perforated or slotted for connection with its adjusting connection, while the cross-blade is furnished with a hook, formed by an inserted block, for detachably connecting it to its actuating devices, all as will hereinafter be explained.

It will be observed that the mold is a complete structure which can be readily removed for inspection, repair, or substitution, and, further, that the mold-blade is supported and guided wholly by the members of the mold, so that all parts are subjected equally to variations in temperature, and the "hanging up" or "sticking" of the mold-blade, incident to the use of separate and more remote guides, is thereby prevented.

The Die-Case.

Strictly speaking, the die-case includes only the series of dies or matrices and the frame in which they are immediately supported; but for convenience the supports and guides in which it travels horizontally for adjustment and vertically for engagement with the mold will be described under this title. The general arrangement will best be understood by reference to Figs. 1 to 8, inclusive, and Fig. 22, the details being found in Figs. 9 to 18, inclusive.

The die-case 20 is not substantially different from that heretofore employed, except as to its attachment to the actuating mechanism. It is composed of an open rectangular frame 21, adapted to receive the die or matrix blocks 22 and furnished with parallel guides 23 on opposite edges. An arm 24, projecting from one end of the frame and furnished with an open traverse groove or socket, serves for connection with the die-centering mechanism.

The die or matrix blocks 22 are rectangular in cross-section, of uniform dimensions, and provided at one end with a die-cavity and at the opposite or upper end with a conical seat 25 for the reception of the centering-plunger. They are mounted on rods 26 in parallel series or columns extending longitudinally of frame 21, said rods passing through transverse perforations in the matrix-blocks and seated at opposite ends in the cross-bars of the frame. The seats for rods 26 extend but

part way through the cross-bar at one end of the frame 21 and entirely through the opposite cross-bar, the rods being retained in position by a detachable cap-piece 27, secured to the frame. As will be seen in Fig. 18, the holes in the matrix-blocks for the reception of rods 26 are of slightly-greater diameter than the rods, and said matrix-blocks are not fitted tightly within the frame 21, but are permitted a very slight motion therein, which, together with the loose fitting upon the rods 26, permits any or all of the matrices to have limited vertical and horizontal play within the frame. The purpose of this movement will later appear.

Frame 21 is supported through its edge guides 23 in ways 28, formed in opposite lower edges of the die-case carrier 29, Fig. 15. To insure accuracy of movement of the die-case in its carrier, the former is provided with ribs 30, parallel with the edge guides 23 and fitted to a central guiding-way 31 on the die-case carrier. Provision is thus made for the accurate movement of the die-case in its carrier in one direction, and to permit of a similar movement of the die-case carrier 29 upon its supporting-frame 32, but in a plane at right angles to the motion of the die-case, said carrier is furnished on its upper side with ways 33 and a central way 34, which are received upon parallel side guides 35 and center guide 36 on the lower face of supporting-frame 32, Figs. 10, 11, and 13.

The centering of any matrix above the mold is effected by a movement of the die-case in its carrier in one direction and of the carrier on its supporting-frame in the other direction, these motions being produced and controlled by the die-centering mechanism.

Provision is made for a vertical motion of the die-case to seat the selected matrix upon the top of the mold, to which end the supporting-frame 32 is attached to the lower ends of two vertical guide-rods 37, passing through the overhanging horizontal portion or bridge forming part of the frame, Fig. 9, said rods being connected together at their upper ends by a cross-bar 38. The guides 39 for rods 37 are preferably in the form of sleeves passing through openings in the frame and adjustably secured thereto by nuts and shoulders, as illustrated in Fig. 9, and said frame 32 is normally upheld against the lower ends of guides 39 by springs 40, each surrounding one of the guides 39 and bearing against a cap 41, adjustably attached to its guide-rod 37, said cap 41 engaging the upper ends of the guides 39 and forming limiting-stops for arresting the downward motion of the supporting-frame 32 when the lower faces of the matrices are brought to the level of the upper surface of the mold and engage the latter, but without pressure thereon. Between the lower ends of the guides 39 and the supporting-frame 32 may be interposed buffer-plates to arrest shock and prevent noise. A stud or pin 42 on cross-bar 38 passes through a lever

43, pivoted at one end in a vertically-adjustable support or rod 44, and a spring 45 is interposed between said lever 43 and the cross-bar 38, while a nut or head on the stud 42 prevents the escape of lever 43. This lever 43 constitutes the medium through which vertical motion is transmitted to the supporting-frame 32 through spring 45 and against the upholding action of springs 40 in lowering the idle die-case, so as to bring the matrix just into contact with the lower face of the mold, the upper ends of the guides 39 forming seats for limiting the downward motion of said frame.

15 The die-case carrier 29 and its supporting-frame 32 are formed with open centers for the passage of the centering-plunger 46. This centering-plunger is formed with a conical or tapered extremity 47, adapted to enter the 20 conical seat 25, formed in the upper end of each matrix-block 22 for the purpose of accurately centering and firmly holding the selected matrix in contact with the upper face of the mold. Hence it is necessary that said 25 centering-plunger should be accurately adjusted and guided. The means adopted for this purpose are best seen in Figs. 9, 10, and 11. Within an opening in the bridge of the frame is located a flanged hub or sleeve 48, against 30 which bear four adjusting-screws 49 for centering said hub, the latter being secured in adjusted position by vertical bolts or screws passing through its flange into the frame. The opposite ends of this hub 48 are furnished 35 with conical seats or bearings, the one to receive the conical head of the guiding-sleeve 50 and the other to receive the conical split sleeve and nut 51 on the opposite end of said sleeve 50, the latter being split longitudinally, 40 (see Fig. 10,) so that by means of nut and sleeve 51 it can be caused to contract, and thereby take up lost motion incident to the wear of the interior surface of said sleeve or the exterior surface of the centering-plunger 46 working therein. Vertical motion is transmitted to the centering-plunger through a head 52 and spring 53, the latter interposed between a shoulder on the plunger and the under side of head 52, while the opposite side 50 of said head contacts with an adjustable nut on the plunger, so that the elevation of the plunger will be effected through positive connections and its depression when centering and seating the matrix through yielding connections.

55 When a comparatively heavy die-case and supporting-frame are employed in conjunction with rapidly-operating actuating devices, it becomes desirable to provide means for temporarily retarding the motions of the die-case while passing from one position of adjustment to another, leaving the parts free, however, when the final centering of the selected matrix is being performed by the centering-plunger. In the present instance this is accomplished by two frictional braking devices, one of which is applied in connection with the ac-

tuating devices operating directly upon the die-case, while the other is applied to the die-case carrier and is operated or thrown out of action by the vertical motion of the die-case, hence may properly be referred to in this connection.

On supporting-frame 32 and in line with each guide 35 is mounted a friction-block or 75 movable section 54, Fig. 12. These blocks are preferably located opposite the centering-plunger, Figs. 11 and 13, and have their inner edges pivotally attached to one of a pair of curved levers 55, Fig. 14. Each of said 80 levers 55 is pivoted to the supporting-frame 32 above the point of attachment to its friction-block 54 and has its free end extended beneath a pin 56, passing through the bridge of the frame. A spring 57, interposed between a shoulder on pin 56 and the stationary frame, operates to hold said pin toward the lower extreme of its vertical movement, which latter is determined by an adjusting-nut on the upper end of the pin. When the supporting-frame 32 is elevated to the position it occupies during the adjustment of the die-case, levers 55, engaging pins 56, elevate the latter against the pressure of springs 57, and said springs bearing upon the free ends of 95 the levers press the latter downward and friction-blocks 54 outward, thereby increasing the frictional resistance to the movement of the die-case carrier upon its supporting-frame 32. When the supporting-frame 32 is depressed to bring the centered matrix down onto the mold, and before the centering-plunger has entered and been seated within the rear end of the selected matrix, pins 56 will be arrested, thereby relieving levers 55 from 100 the pressure of springs 57, thus withdrawing the additional frictional resistance due to the pressure of blocks 54, so that the die-case carrier will be free to move laterally under the influence of the centering-plunger.

110 The vertical motions communicated to the supporting-frame 32 through its lever 43 and to the centering-plunger 46 through its head 52 are derived from a single actuating-lever 58, whose furcated end embraces head 52 between upper and lower shoulders thereon, while the free end of lever 43 is connected to said lever 48 by a link 59 at a point intermediate the head 52 and the fulcrum of said lever, Figs. 3, 5, and 7. By means of these 115 connections the vertical motions communicated to the die-case and centering-plunger, although derived from the same prime mover—*i. e.*, lever 58—and coinciding both as to time and direction, differ as to extent of travel—120 that is to say, the centering-plunger travels in the same direction, but at a greater speed than the die-case. This permits the centering-plunger to be entirely withdrawn from the matrix when in elevated position and to overtake and enter the matrix during the downward motion of the die-case.

125 The horizontal adjustments of the die-case are performed while it is held in elevated po-

sition, as indicated in Figs. 7 and 9, with the centering-plunger entirely clear of the matrices. As soon as this preliminary centering of the matrix has been completed the load-
 5 arm of lever 48 is advanced toward the mold, thereby lowering the die-case until the latter is arrested by its limiting-stops, which occurs when the matrix-block just makes contact with the mold, but without pressure. In the
 10 meantime the centering-plunger will have overtaken the die-case and entered the centering-cavity in the preliminarily-centered matrix, giving the latter its final adjustment, and the plunger continuing to advance after
 15 the die-case has been arrested presses and holds the centered matrix firmly in position on top of the mold. During this final centering of the matrix the retarding frictional devices operating upon the die-case and its car-
 20 rier have been relaxed or withdrawn, leaving the die-case free to respond to the centering action of the plunger, which action may only affect the selected matrix, or may extend to the die-case and its carrier, according to the
 25 degree of accuracy with which the die-case-centering mechanism operates in effecting the preliminary centering.

Die or Matrix Centering Mechanism.

30 As before explained, the centering of the matrices is effected by movements of the die-case in a horizontal plane on lines intersecting at right angles, the motions in one direction being communicated directly to the die-
 35 case through arm 24 and those in the other direction to the die-case carrier 29. It is obvious that these motions may be effected either separately or simultaneously, or that either may be employed singly, according to
 40 the location of the die-case at the time when the adjustment is to be made. Thus in the example illustrated in the drawings the types are graded as to width into fifteen sizes, whose increments are uniform throughout the
 45 series, and the matrices are arranged in fifteen parallel lines, extending transversely of the die-case, each line being composed of a complete series of fifteen matrices, representing characters increasing progressively in
 50 width from one end of the line to the other. This brings all the matrices representing type of the same body width into alinement longitudinally of the die-case, there being as many columns of matrices as there are sizes of types, the column containing the widest type being located at one extreme of the series of traverse-lines and those of the smallest at the opposite extreme. If, for example, the right-hand column is assigned to the type of maximum width, the next succeeding column to the left will contain characters of the next smaller dimensions, and so on throughout the series. It will be seen, therefore, that the motions of the die-case in one direction will
 60 correspond to a change in position from one column to another, which is the same as the

change from one size to another, while the movements of the die-case in the other direction from line to line will be equivalent to the selection of a particular letter in the column. 70 To effect and control these motions of the die-case according to an organized system is the purpose of the die-centering mechanism.

Although connected for conjoint action, there are, in effect, two controlling mechanisms, the one operating upon the die-case directly and the other upon the die-case carrier; but inasmuch as these two mechanisms are in the main duplicates a description of one will serve in a measure for both. As organized in the present machine each of these mechanisms is made up of five elements or groups—to wit, first, a primary controller or fixed gage; second, a primary positioning or gaging mechanism; third, a secondary controller or shiftable gage; fourth, a secondary positioning or gaging mechanism, and fifth, translating devices.

The primary controller or fixed gage.—This consists of a series of pins or stops 65, arranged in fixed relation to each other at distances apart equal and corresponding to the distance between the center of one line or row of matrices and the center of the next adjacent line or row. Referring, for example, to the mechanism immediately controlling the die-case, Figs. 27 to 30, inclusive, whose movements correspond to a shifting from one line of matrices to another, each of the pins or stops 65 corresponds in relative 90 position and arrangement to one line of characters in the die-case, while the stops or pins of the other series, Figs. 55 to 59, that belonging to the die-case carrier 29, correspond in position and arrangement to the several 100 columns of matrices.

In the example illustrated provision is made for dealing with a die-case containing two hundred and twenty-five matrices or a square containing fifteen lines of fifteen characters 110 each. Hence there are fifteen stops or pins in each series.

The terminal pin or stop (marked 65*) is fixed, while all of the others in the series are movable or so arranged that any one may be 115 brought into position for engagement by the coöperating portion or portions of the primary positioning mechanism. In the preferred form of embodiment the movable pins 65 of each series are pneumatically controlled, 120 as hereinafter explained, to which end each pin is provided with a piston-head 66 and retracting-spring 67, Figs. 42 and 63, arranged in a cylinder formed in a supporting-plate 68. For convenience of construction this supporting-plate 68 is detachably secured to the top 125 plate of the frame and is formed with the series of cylindrical perforations constituting the cylinders, the lower end of each cylinder registering with a supply-pipe passing through 130 the bed-plate. Inasmuch as it is very desirable that the pins should be accurately lo-

cated, their upper ends are passed through and guided by a plate 69, overlying the cylinder-plate 68.

The primary function of the series of pins 65 is to furnish a controllable gage for designating and locating the position of each line of matrices contained in the die-case.

The primary positioning or gaging mechanism.—The principal function of this mechanism is to adjust the position of the secondary controller or shiftable gage to correspond with a designated pin or stop 65 of the primary controller or fixed gage, and the preferred means for accomplishing this will next be described.

Supported to reciprocate upon a fixed guide or bar 70, above and parallel to plate 69, are arranged a pair of jaws or clamping members 71 71*. One of these jaws 71 is provided with a plate or flange 72, lying in the paths of the several pins 65 when elevated or projected into operating position, while the under side of the opposing jaw 71* lies in a plane above the extremities of the pins. If now any one of the series of pins 65 is elevated or if the movable pins remain down and the fixed pin alone stands in the path of jaw 71 and said jaw is moved until its plate 72 contacts with the elevated pin, it is obvious that the position at which said jaw is arrested will coincide with that of the pin against which it bears, and if the opposite jaw 71* is brought up into contact with the first-named jaw the line of division between the two jaws will coincide as to position to that of the selected pin. A novel system of actuating devices has been devised for giving motion to these two jaws, whereby during each revolution of the driving-shaft the two jaws shall separate or assume positions at opposite extremes of their movements, and in closing or moving toward each other from these extreme positions that one of the jaws which is to contact with the primary controller or fixed gage shall be first advanced and its motion continued until arrested by the designated stop, whereupon the other or opposite jaw will be set in motion and caused to advance until it contacts with the previously-arrested jaw. The mechanism for effecting these movements comprises two levers 73 and 74, connected together at their inner ends by an adjustable link 75 and each having its outer end pivoted to one of the jaws 71 71*. Lever 73 is pivotally attached to a link 76, whose opposite end is pivotally supported upon a post secured to the main frame, while lever 74 is similarly connected by a link 77 to a post or pin carried by a horizontal bell-crank lever 78. It will be observed that this system of levers is furnished with but one fixed point of support or center of motion—to wit, the post to which link 76 is connected—that motion is transmitted from the prime mover or driver (bell-crank 78) through its connection 77 with lever 74, the latter being bodily mov-

able toward and from the fixed pivot of lever 73 by virtue of its connection with the latter, and that both levers 73 74 are at the same time capable of oscillating about the points 70 of attachment to their respective links 76 77. It results from this arrangement that starting from the position shown in Fig. 27, with the jaws open, when the actuating-lever 78 is moved to the left it will operate first to advance the right-hand jaw 71, or that provided with the edging-plate 72, until the latter makes contact with and is arrested by one of the elevated pins or stops 65 of the primary controller or fixed gage. During this motion lever 80 75 73 remains stationary, the jaw attached thereto remaining against the stop at the outer extreme of its movement, where it is held by a spring 79, connected to lever 73, intermediate link 76 and said jaw, so that the pivot connecting lever 74 to link 75 is for the time being the fulcrum of said lever. As soon, however, as the outer end of lever 74 is arrested by the contact of its jaw with the stop-pin the fulcrum is shifted to the outer end of the said lever 90 and the inner end becomes the power-arm, from which motion is transmitted through connecting-link 75 to the inner end of lever 73, thus causing the latter to turn upon the pivots of its link 76 and overcoming the tension of the spring, moving the opposite jaw 71* up against the stationary jaw. As will be seen most clearly in Figs. 2, 22, and 25, these lever systems are duplicated for effecting the two motions of the die-case, each system being connected to one arm of the bell-crank lever 78, and in order to equalize the spring action on the corresponding levers 73 for retracting said levers and opening the jaws upon the reverse movement of the bell-crank spring 79 is attached to one end of a lever 80, pivoted upon a fixed support on the frame, while the opposite end of said lever is attached to another spring 81, the latter being in turn connected (through a bell-crank lever 82, carried by bell-crank 78 and link 83) to lever 73 at a point intermediate its link 77 and the connecting-link 75. Springs 79 and 81 are under initial tension, and they are connected through lever 80 for the purpose of 105 equalizing their action upon the two systems.

Although the two systems of levers above referred to are practically the same, there is a slight difference in the arrangement of the connections, and that is lever 74, which is 110 connected to the jaw 71, is pivotally connected to the post on the frame instead of to bell-crank 78, while lever 73 is pivotally connected to bell-crank 78, and the spring-retractor is attached to the inner arm of lever 73, from 115 which it results that the movement of lever 78 in a direction to close the jaws causes the inner end of lever 73 of the die-case carrier system to advance, and acting upon the inner end of lever 74 swings the latter and carries 120 its jaw 71 forward until it encounters the stop-pin, after which the inner end of lever 73 be-

comes the fulcrum - point about which its movements take place in advancing the opposite jaw 71*.

Both sets of jaws 71 71* open simultaneously preliminary to the setting of their primary controllers, but each operates independently with respect to the latter—that is to say, the point at which one set of jaws is arrested does not in any degree affect the position or movement of the other set of jaws.

The secondary controller or shiftable gage.—Having explained how the primary positioning or gaging mechanism is operated and governed by the primary controller, the next in order is the secondary controller or shiftable gage, whose function it is to control the position of the secondary positioning or gaging mechanism. It consists of a movable block or abutment 84, Fig. 43, located between jaws 71 71* and mounted to reciprocate parallel therewith, with a locking device for effecting final adjustment and holding it in position. To this end the block 84 is supported upon a slide 85, the latter mounted to reciprocate in guides parallel with the movements of jaws 71 71* and furnished with a regular series of centering and holding detents, composed in the present instance of a series of rack-like teeth 86. One or both of the jaws 71 71* of each set is cut away or recessed to form a seat for the reception of this secondary controller or shiftable gage 84, said seat being of such dimensions that when the jaws are closed the said shiftable gage will be held therein after being brought to position by the movement of either one of the jaws constituting a set. Preferably but one jaw 71* of each set is recessed, the face of the opposite jaw 71 forming one wall of the recess, and if desired the sliding jaw 71 may be provided with a pivoted and spring-retracted engaging lever 91, Figs. 22 and 79, whose free end stands in line with the secondary controller 84, thus forming a yielding contact for engaging and locating said controller.

The shiftable secondary controller or gage occupies at all times a position intermediate the jaws 71 71*, and no matter where located at the time the jaws are separated it will by 50 the closing of the jaws be brought to a position corresponding with that of the primary controller or fixed gage.

To insure a very accurate adjustment of the secondary controller after it has been brought to position and to lock it against movement while the primary controlling mechanism is being reset or opened preliminary to the next adjustment, a locking-bolt 87, adapted to enter between the converging walls formed by rack-teeth 86, is employed for each of the secondary controllers. Both locking-bolts 87 are operated simultaneously to center and hold or release the secondary controllers through the agency of a bell-crank lever 88, Fig. 33, to which end each locking-bolt is furnished with a longitudinally-adjustable stem 89, carrying a spring and sliding head 90 between limit-

ing-stops. An arm of lever 88, engaging said sliding head 90, acts through its compression-spring to advance the locking-bolt and hold it in engagement with the notches in the secondary controller, while the retracting movement is positively effected by engagement with the shoulder on stem 89.

The secondary positioning or gaging mechanism.—This acts directly in connection with the secondary controller or gage 84 after the latter has been set or adjusted. Although the two mechanisms are substantially the same in construction and operation, it will be more convenient to consider them separately in order to distinguish between them in other connections. Each comprises two jaws or oppositely-reciprocating blocks adjacent to the jaws 71 71* of the primary positioning or gaging mechanisms, those pertaining to the mechanism acting directly upon the die-case being numbered 92 and 93, Figs. 23, 24, 27 to 30, inclusive, and 42, and those pertaining to the die-case-carrier-operating mechanism being numbered 94 and 95, Figs. 57, 62, and 63. Each set of jaws 92 93 and 94 95 has one of the secondary controllers 84 located between its members in position to be engaged thereby, the said jaws being supported in guides directly above the slide or support 85, carrying the movable block or abutment constituting said secondary controller 84.

Each pair of jaws 92 93 and 94 95 is controlled and actuated to open or move away from and to close or engage upon its controller 84 by a system of levers corresponding generally with those which actuate the jaws 71 71* of the primary positioning or gaging mechanism. Thus jaw 92 is pivotally attached to the outer end of a lever 96, the latter connected at a point intermediate its ends by a link 97 to a pivot on bell-crank 78. Jaw 93 is pivotally attached to the outer end of lever 98, which latter is connected at a point intermediate its ends by a link 99 to a fixed pivot on the frame, and the two levers 96 and 98 are connected at their inner ends by an adjustable link 100. In like manner the levers pertaining to jaws 94 95 are connected to the opposite arm of bell-crank lever 78—that is to say, lever 101 is connected at its outer end to jaw 94 and by a link 102 to a fixed pivot on the frame, while its inner end is connected by an adjustable link 103 to the corresponding end of lever 104, carrying opposite jaw 95, said lever 104 being in turn connected by a link 105 to the bell-crank lever 78.

By reference to Figs. 22 and 25 it will be seen that the levers of the secondary positioning or gaging mechanisms are connected up oppositely to the levers of the primary positioning or gaging mechanism with which they are associated—that is to say, (referring, for example, to the devices pertaining directly to the die-case movement,) while the outer lever 73, or that most remote from the mold, is connected to the pivot on the frame, the

corresponding lever 96 of the secondary positioning-jaws is connected to the bell-crank lever 78, the opposite levers of the two pairs being connected, respectively, to bell-crank lever 78 and to the fixed pivot on the frame. This reversed order of connection is adopted in order that the two sets of jaws may be moved simultaneously in opposite directions, so that while one set of jaws is closing upon its stop or controller the other set will open in order that its stop or controller may be set, and vice versa.

The secondary controller 84 having been set in position by and during the approach of jaws 71 71* and jaws 92 93 and 94 95 of the secondary controlling mechanism having been opened or separated, when the motion of the driving-lever 78 is reversed to open jaws 71 71* it will bring the jaws of the secondary controlling mechanism together upon opposite sides of the secondary controller 84, the latter serving to determine the point within its range of adjustment at which the jaws of the secondary controlling mechanism shall be brought together.

The translating devices.—The next and last element in this series includes the translating devices, or those through which the adjustments thus effected are made operative upon the die-case and the die-case carrier.

It will be remembered that in addition to the movement from line to line or in a direction longitudinally of the die-case the latter is susceptible of a transverse motion communicated through its carrier 29. Hence provision must be made in the die-case-shifting mechanism to accommodate these lateral motions. First, as to the longitudinal movements of the die-case. In the supporting-plate 68 and parallel with the pins in which jaws 92 93 of the secondary controlling mechanism is formed is a guide or way for the reception of a slide 106, Figs. 31, 42, and 44, provided with a cross-head 107. This cross-head rides upon ways 108, Figs. 23, 38, 39, and 56, and is furnished with an upwardly-projecting rib 109 and two forwardly-projecting arms or seats 110. A yoke-plate 111, having a slot or opening wider than rib 109, fits over the latter and rests upon arms 110, said yoke being firmly secured in position by screws. The purpose of this construction is to furnish a cross-bar or seat at right angles to slide 106, adapted to receive and fit between the shoulders or engaging walls of the slot formed in arm 24 of the die-case frame 21, so that the latter will be free to move across the path of slide 106, but will follow accurately the longitudinal motions of said slide. At the same time the construction is one which permits the ready application and removal of the die-case. It is obvious that the yoke-plate 111 and slide 106 might be formed integral; but inasmuch as the greatest amount of wear occurs upon the yoke and it is desirable that it should be made with true surfaces it is preferably formed separate from its supporting-

slide and attached thereto in the manner explained in order to secure fixety of adjustment.

A headed rod 112 is adjustably secured to cross-head 107, as by means of a split socket and pinching-screw, said rod extending parallel with slide 106 and through an opening in jaw 93 of the secondary positioning mechanism, thus bringing its head intermediate jaws 92 93 and in position to be engaged by the latter.

Inasmuch as the die-case carrier is given a lateral motion, its horizontal movements being all in one direction, the translating devices are connected directly to said carrier, Fig. 15. Hence a headed rod 113 is adjustably attached to a split socket on the die-case carrier 29. As the point of attachment of the rod 113 to the die-case carrier is slightly to one side of jaws 94 95, though parallel therewith, its headed end is received between the proximate faces of a lateral projection 114 on jaw 94, Fig. 63, and a wing or projection 115 on jaw 95, Fig. 62. This arrangement is not substantially different from that of the translating devices for the die-case and is only made to accommodate the parts to slight changes in position due to the presence of other elements in the machine.

It may here be remarked that slide 106 furnishes a convenient point of application for the friction device hereinbefore mentioned as the complement of friction-blocks 54, operating upon the die-case carrier. To this end a friction plunger or block 116, Figs. 22 and 23, is arranged to bear upon the upper surface of slide 106 and is operated upon by lever 117, to whose outer end is connected a link 118, Fig. 40, passing upward through a lug on actuating-lever 58, said lug engaging a shoulder beneath it on the rod and a spring above it, so that during the downward motion of the actuating-lever to depress and center the matrix the pressure of friction-block 116 will be released, and when said actuating-lever is elevated, while the adjustment of the matrix is being effected, the friction-block will be held, under the elastic pressure of its spring, in contact with slide 106, thereby exerting a limited degree of resistance to motion.

The operations of the die-case-centering mechanism are illustrated in the diagrammatic views, Figs. 27 to 30, inclusive. Fig. 27 represents the die-case-actuating devices immediately after a cast has been made. The secondary controller 84 has been located, and jaws 92 93 of the secondary positioning or gaging mechanism have been closed upon it, and in so doing have, by engagement with the head of rod 112, brought the die-case to position. Locking-bolt 87 has been withdrawn, and the parts are in position for the next succeeding adjustment. Jaws 71 71* of the primary positioning mechanism being open—that is, separated—the primary controller or pin 65, representing the position in

the line of the next character to be formed, is projected into the path of jaw. Assume, for example, that the next character or matrix is the first in the line, or that represented by 5 the first of the series of pins 65. Said pin is projected into the path of jaw 71 and bell-crank lever 78 is operated to close the jaws and at the same time open or separate the jaws of the secondary controlling mechanism. 10 The result is, as indicated in Fig. 28, the translating device is released and the secondary controller 84 brought to its new position and locked. A reversal of the motion of lever 78 separates jaws 71 71* of the primary 15 positioning mechanism and closes jaws 92 93 of the secondary positioning mechanism upon the secondary controller 84, at the same time shifting the translating devices from the former position (indicated in Fig. 27) to the new 20 position of the secondary controller, as indicated in Fig. 29. In like manner the adjustment is made for each position and is determined by the primary controllers. In Fig. 30 the shifting of the secondary controller to 25 a position corresponding with the eighth pin is represented.

Corresponding movements of adjustment are performed with respect to the centering mechanisms operating upon the die-case carrier, and it will be apparent that by the joint action of both mechanisms any matrix in the series may be brought into position above the mold by merely selecting one pin corresponding to the line and another corresponding to the column.

It will be noted that the adjustments of the die-case and of its carrier from one position to another are performed directly, without necessity of returning either the die-case or 40 its carrier to a zero position, whereby excessive motion is avoided and the traverse of the die-case is reduced to the minimum, and where the same letter is repeated no lateral motion of the die-case in either direction is required, it 45 remaining in one position, although its actuating devices operate as before, but without moving the die-case.

So far as the mere operation of moving the die-case to correspond with the various positions indicated by the primary controller or gage is concerned, the translating devices might be connected to one of the jaws of the primary controlling mechanism or to the secondary controller 84, provided both jaws 71 71* 50 were adapted to contact with the primary controller lying between them, as is done in the case of the jaws of the secondary controlling mechanism, where no spring is required; but such an arrangement would be inadequate to 55 deal with a defective record-strip such as would cause the simultaneous elevation of two or more pins 65 between the jaws, and owing to the necessarily rapid motions of the jaws the shocks and strains upon the primary 60 controller incident to inertia would tend to disturb the delicate adjustments requisite for the proper centering of the matrices. It is

with a view to effecting an improvement in these features that one jaw only of the primary controlling mechanism is arranged to 70 engage the primary controller or gage and the spring applied so that in the event two or more stop-pins 65 are projected into the path of the jaw the latter will engage the first one, the opposite jaw moving over the pins and 75 contacting with the arrested jaw. Moreover, by employing the two controlling mechanisms more time is allowed for effecting the necessary movements of the die-case, and the shocks incident to the arrest of the die-case 80 are borne by the secondary instead of by the primary gage.

Normal Mold-Adjusting Mechanism.

Accurately speaking, this mechanism might 85 be said to include only those devices which operate to determine the position of the mold-blade when in casting position; but inasmuch as they are directly associated with the mechanism to which the mold-blade is connected 90 and by which it is moved, both for ejecting the type from the mold and for returning it to casting position, it has been thought proper to describe the connections for moving the mold-blade under this head.

Referring particularly to Figs. 23, 38, 39, 40, 44, and 56, it will be seen that the mold-blade 4 is attached to the front end of a slide 120 by a detachable cross-pin 121, passing through arms of the slide and the perforation 100 in the rear of the mold-blade. This slide 120 has a vertical opening in rear of the point of attachment of the mold-blade for the accommodation of a stop or abutment for limiting the rearward movement of the said mold-blade, and the rear end of said slide is connected to a rod 122, Fig. 44, passing through the frame below slide 106. This rod 122 carries two springs 123 and 124, the former engaging a shoulder on the rod and the latter a 110 nut or collar on the outer or free end of the rod. The interval between spring 123 and the shoulder on the outer end of the rod is occupied by three sleeves—to wit, a headed or flanged sleeve 126 next spring 123, a sleeve 115 125 on the outer end of the rod, and a wider sleeve 125* intermediate sleeves 125 and 126. Spring 124, surrounding sleeve 125, engages a collar 127, riding loosely on said sleeve, to hold it against the end of sleeve 125*. Embracing sleeve 125*, which latter is flattened on opposite faces, Fig. 23, is the furcated end of a lever 128, the latter being somewhat narrower than the interval between collars 127 and the flanged head of sleeve 126, and said 125 lever is connected by a link to its actuating-lever 178, Fig. 2. The operations of these parts will be explained in connection with the normal mold-blade-adjusting mechanism. It is sufficient for present purposes to state 130 that they constitute the means for communicating reciprocating movements to the mold-blade.

Beneath slide 120 and guided to recipro-

cate in ways parallel therewith is another slide 129, Figs. 44, 47, and 48, which is furnished with a stop or abutment 130, standing vertically in the opening in slide 120 and occupying a position immediately in rear of the mold-blade 4. For convenience of adjustment the engaging face of this stop or abutment is rendered adjustable, as by the application of a set-screw 131 at this point, one end of the latter standing in line with the rear end of the mold-blade, as seen in Fig. 44. It is by the setting or adjusting of this stop or abutment 130 during the forward or ejecting movement of the mold-blade that the width of the mold is determined for the next type, said stop operating to intercept the rearward motion of the mold-blade at the proper point, and these operations are performed through the medium of what is herein termed the "normal wedge" 132, Fig. 50, and the lower transfer-block 133, Fig. 46, as will presently appear.

Slide 129 is furnished on the under side with a shoulder or abutment, between which and a fixed surface on the frame are arranged the normal wedge 132 and its transfer-block 130, the two latter extending in a plane substantially at right angles to the direction of motion of said slide. (See Fig. 44.)

The normal wedge 132 and its transfer-block 133 together constitute a pair of reversed wedges, either or both of which may be varied as to its angular dimensions in fixing the size of and the ratio of variation between the types of the particular series being made. In order, however, to minimize the number of parts or elements to be changed in order to adapt the machine to different kinds or systems, as in changing from brevier to pica or from the American to the English system, the transfer-block is constituted the constant and the normal wedge the variable factor.

The longitudinal reciprocations of the transfer-block are uniform in extent, and its principal function is to set the abutment-slide 129 after the normal wedge has been adjusted. Hence its angle is or may be constant for all kinds of type, and in order that its action may be uniformly and properly gaged the fixed 50 abutment (preferably formed by a detachable plate 134) has its face inclined to correspond with the engaging face of the transfer-block, while the proximate faces of the normal wedge and the transfer-block are also given the same 55 angle of inclination.

If the machine is constructed to deal with but one kind of type, the angle of the normal wedge will be calculated so that each of its fifteen degrees of motion will produce a one-unit 60 variation in the position of the abutment-slide, and in such case either or both faces of the wedge might be inclined to the direction of its motion; but when, as in the example illustrated, the machine is adapted to form 65 different kinds of type the face of the normal wedge next the abutment-slide 129 is tapered in order that any one of a series of normal

wedges with different degrees of taper suited to the different kinds of type may be inserted between the abutment-slide and the transfer-block and be made to work in harmony with the latter by reason of the uniform angle of the surface contacting with said transfer-block. The face of the normal wedge next the abutment-slide thus becomes the variable element, and by increasing or diminishing its angle the ratio of variation between different-sized type of the same series can readily be calculated and provided for.

To accommodate normal wedges of various angles and dimensions, the abutment-slide 129 carries a self-adjusting contact in the form of a block 135, Fig. 49, whose rear surface is curved to fit within a seat in slide 129, and it is held from displacement by a pin on 85 said slide riding in a groove in one end of the block.

It will readily be seen that by changing the position of either the normal wedge or its transfer-block the slide 129, carrying abutment 130, can be adjusted or set so as to intercept the mold-blade at any desired point in the line of its backward travel.

Both means of adjustment are utilized in the present machine, the one manual and the other automatic.

The manual adjustment is applied to the transfer-block and includes the devices for regulating the position of the transfer-block when at one extreme of its movement—its operating position.

The automatic adjustments are effected through the normal wedge alone, the transfer-block being utilized for the purpose of moving the abutment to position after the 105 normal wedge has been set and to shift the action of the normal wedge into connection with the abnormal or justifying mechanism, as will presently appear. To accomplish this, it is required that the transfer-block 133 110 should when retracted or inactive occupy the position indicated by dotted lines in Fig. 55, thus leaving the normal wedge free for adjustment, so that after the latter operation has been performed the transfer-block may 115 be drawn to the position indicated by full lines in Fig. 55, thereby effecting the proper adjustment of the abutment-slide. The mechanism for bringing the transfer-block 133 into action at the proper times will be explained in connection with the justifying mechanism. At present the description will 120 be directed to the means for adjusting or setting the normal wedge.

The angle of the normal wedge is adjusted 125 to the particular system adopted. Thus if the type-bodies are arranged in fifteen groups or divisions, with a uniform rate of increase, the taper should be such that fifteen equal degrees of movement will cover the entire 130 range of variation in body width from the widest to the narrowest. Such being the case, it is only necessary in order to effect an adjustment of the mold corresponding to the

width of type represented by the several columns of matrices in the die-case to shift the normal wedge so that its position shall coincide with that of the column in which the selected character to be formed is found. To effect this adjustment rapidly, accurately, and in harmony with the motions of the other mechanisms, the jaws 94 95 of the secondary positioning or gaging mechanism acting upon the die-case carrier are utilized, to which end each of said jaws is provided with a horizontal extension or wing 136 and the normal wedge 132 is furnished with a pin or projection 137, fitting the interval between said wings when jaws 94 95 are in closed position. It will be borne in mind that these jaws 94 95 are brought together upon the secondary controller 84 in locating any column of matrices over the mold and that the column is determined by the selected primary controller 65. Hence the same devices which operate to position the die-case carrier are utilized to effect a corresponding movement or adjustment of the normal wedge, thereby adjusting the width of mold-cavity to the selected column of matrices. Inasmuch as accuracy of adjustment is necessary the normal wedge is further provided with a series of equally-spaced and accurately-located transverse grooves 138 for the reception of a locking and centering pin 139, Fig. 38, the latter passing through a split adjusting-sleeve 140 and being connected at its upper end to the lever 58, by which the die-case is depressed into contact with the mold. Lever 58 acts positively against a shoulder on the upper end of the locking-pin to raise the latter out of engagement with the normal wedge, and it operates yieldingly through a spring to depress and hold said pin in engagement with the normal wedge after the latter has been adjusted and while a cast is being made. While the normal wedge is being thus held, the setting devices or wings 136 open or separate preparatory to the next succeeding adjustment, which latter is effected by simply moving the wedge from the last previous point of adjustment to the next instead of carrying it back to zero between succeeding adjustments.

I have thus far considered those adjustments of the mold-blade which correspond to the normal variations in the body widths of the type and to the fifteen columns represented by matrices in the die-case, and the same is true as to such space-type as correspond to any of the fifteen dimensions mentioned, it being of course understood that for space-types the matrix-block is not provided with a die-cavity; but the more important or at least equally important element in the machine is the provision for abnormal adjustments, whereby justified lines of type are produced.

65 *The Justifying Mechanism.*

This embraces, in addition to the normal wedge 132, the two justifying-wedges 141 and

142, Figs. 51 and 52, and a transfer block or wedge 143, operating in conjunction with the slide carrying the mold-blade stop or abutment 130. Although a single justifying-wedge might under certain conditions be employed, two are preferred as affording a greater range and finer adjustment. The range of motion of the two justifying-wedges 75 141 and 142 is the same as that of the normal wedge and, like the latter, is divided into fifteen equal periods or degrees. In the example given one wedge 141 has a taper giving an adjustment equal to .0005 of an inch for each 80 degree of longitudinal motion, while the other wedge 142 has a taper giving an adjustment of .0075 of an inch for each degree of motion. The transfer-block 143 is located directly above transfer-block 133 and occupies a position between the justifying-wedges and the normal wedge. 85

To effect justification, it is required that the transfer block or wedge 133 should be held out of action, the transfer block or wedge 90 143 be brought into action, and either one or both justifying-wedges 141 142 be adjusted to position in order that the variation in the position of the mold-blade abutment due to the action of the justifying-wedges may be superadded to the adjustment effected by the normal wedge when a space-type is to be produced. First, as to the means for determining which set of adjusting devices shall be operatively connected with abutment-slide 100 129, the normal wedge alone or the normal and justifying wedges. The selection is made through the medium of transfer-blocks 133 and 143, the forming serving to connect the normal wedge alone and the latter the 105 normal and justifying wedges. The actuating mechanism for these parts is such that one or the other, but not both, of the transfer-blocks shall be operative during each revolution of the driving-shaft, thus rendering 110 active the system of adjusting devices to which it pertains by interposing the wider portion of the transfer-block between the controlling adjusting element or elements and the movable mold-blade abutment. 115

What may be regarded as the starting positions of the two transfer-blocks are those which they assume after the cast has been made and preliminary to the next adjustment, at which time both transfer-blocks 120 have their wider portions projected beyond or to one side of slide 129, their smaller or narrower portions lying beneath said slide, thereby relieving the latter from the pressure of the wedges and permitting it to be retracted 125 by a spring 144, Fig. 23, as indicated in Fig. 57. It is while this condition exists that the adjusting-wedges are set in the event a change of adjustment is to be made; but if not they retain their positions, although for the time 130 rendered inactive.

The withdrawal of the transfer-blocks from operating position is accompanied by a movement of abutment-slide 129 under the influ-

ence of spring 144, thus maintaining contact between the sliding surfaces and preventing the admission of dirt or the formation of a film of oil, which might interfere with the accurate adjustment of the mold-blade.

It is important that the two transfer-blocks 133 and 144 should be susceptible of accurate adjustment, more especially in their forward or active positions, and that they should be loosely or flexibly connected to their actuating devices, both to enable ready removal and replacement and to render their action as independent as possible of that of their connected actuating devices.

First, as to adjustment. When in operating position, transfer-blocks 133 and 143 are brought into engagement with a fixed abutment or limiting-gage for accurately determining their position relative to abutment-slide 129 and the adjusting-wedges. Such a limiting-abutment, with capacity for accurate adjustment, is present in wedge 145, Figs. 38 and 54, whose vertical face stands at right angles to and across the line of movement of the inner ends of the two transfer-blocks. This wedge is mounted in a detachable frame 146 and is adjustable vertically by means of rod 147 and nuts 148. To provide independent adjustment for the two transfer-blocks, one of them—in the present instance the upper one, 143—is furnished with an adjusting member, such as screw 149, for contacting with wedge 145. Thus slight variations in the positions of the two transfer-blocks with relation to the fixed limiting stop or abutment can be effected.

The transfer-blocks are reciprocated horizontally through the medium of two rods 150 151, lying one above the other and each provided with a hooked extremity for engagement with a corresponding hook on the inner end of its transfer-block. The connection is one adapted to permit a limited degree of lateral motion of the transfer-block with relation to its connected actuating-bar, such as is occasioned by the adjustment of the normal and justifying wedges. The two rods 150 151 pass through an opening formed in the lower end of a transverse or vertical locking-rod 152, Figs. 35, 36, and 39, and each of said first-named rods is furnished with a notch 153, so related to the movements of the transfer-blocks that when at the extreme of their outward movements—that is, with their wider ends most remote from the abutment 145—the notches 153 will stand in line with locking-rod 152 in position to be entered and held by the latter. Actuating-rod 150, carrying transfer-block 133, has its notch 153 in its lower face, while the corresponding notch in the actuating-rod 151 of transfer-block 143 is in the upper face thereof, so that when locking-rod 152 is depressed it will enter the notch in actuating-rod 151, thus holding the latter and its transfer-wedge 143 against longitudinal motion, while permitting the lower actuating-rod 151 and its transfer-block to move freely

through the opening in locking-rod 152; but when said rod 152 is elevated the conditions will be reversed, actuating-rod 150 being held 70 and 151 permitted to reciprocate. The interval between the two locking-shoulders of rod 182 is slightly less than the aggregate thickness of rods 150 151, so that the release of one rod will not take place until after the 75 other has been engaged. The movements of locking-rod 152, whereby one or the other of the two actuating-rods 150 151 is locked in position, take place when the transfer-blocks are both at the outer extremes of their movements and both notches 153 are in line with locking-rod 152, and the motions of the latter are derived from lever 58 through a controllable system of actuating mechanism which will next be described. The prime 85 factors of this mechanism are a main driver or reciprocating member, such as the lever 58, and controllable connections intermediate said main driver and the locking devices or rod 152, whereby the latter can at proper 90 intervals be thrown into engagement with either of the rods 150 151, thereby arresting either transfer-block 133 143, so as to hold it out of action, leaving the other free to act. A competent mechanism for this purpose is 95 illustrated in Figs. 34 to 37, 39, and 40. The locking-rod 152, guided and supported in frame 146, has its upper end attached to a block or cross-head 154, the latter riding vertically upon a guide-pin secured to the frame. 100 This cross-head 154 extends laterally over a lever 155, also pivoted to the frame 146, the said lever and cross-head being united by a yielding connection competent to hold the locking-rod at either extreme of its movement 105 under elastic pressure. Such a connection is formed by guide-rod 157 passing loosely through cross-head 154 and having its lower headed end seated in lever 155. Rod 157 is provided immediately above its head with a loose washer 158, engaging lever 155, and between said washer and a loose sleeve is interposed spring 156, through which the vertical motion of lever 155 is transmitted to the locking-rod. Between a fixed portion of frame 110 146 and washer 158 is interposed another spring 159, which operates to depress guide-rod 157 and lever 155, and thus hold the locking-rod 152 toward the lower position or in engagement with the actuating-rod 151 of the 115 justifying transfer-block 143, which is its usual or normal position, as when character-types and normal spaces are being produced. The outer or free end of lever 155 carries a pivoted trip 160, Fig. 34, whose upper end 120 passes through one of a series of slots 161, formed in a lateral horizontal arm or projection of lever 58, Figs. 22 and 40. The upper surface of this arm or projection is stepped, (see Fig. 40,) and the upper end of the pivoted trip 160 is furnished with an adjustable 125 collar or nut, which latter when moved to a position above the higher step or section of lever 58 will be engaged by the latter as it

rises, thereby elevating lever 155 and raising the locking-rod 152 into engagement with the actuating-rod 150 and out of engagement with actuating-rod 151. This action takes place 5 only when the pivoted trip is moved so as to bring its shoulder above the higher portion of lever 58 and until such motion takes place, and as long as the pivoted trip remains above the lower step or at the opposite end of 10 the slot no motion will be communicated to locking-rod 152 by the elevation of lever 58, which action, it will be remembered, takes place after the cast has been made and preliminary to the readjustment of the die-case 15 for centering the next succeeding matrix. A spring 162 operates to hold the pivoted trip 160 normally retracted or out of engagement with the elevating portion of lever 58. Immediately in rear of pivoted trip 160 is mounted 20 a trip-lever 163, one arm of which bears against the pivoted trip 160, while the other arm engages a plunger 164, working in a cylinder formed in frame 146. When this plunger is elevated, it operates through trip-lever 25 163 to tilt the pivoted trip 160 and throw its upper end into engagement with the elevating portion of lever 58. Hence said plunger serves as a controllable means for effecting the transfer of the locking-rod 152 from one 30 actuating-rod 150 151 to the other. The descent of lever 58 restores the parts to normal position with locking-rod 152 in engagement with actuating-rod 143.

Assuming the normal wedge alone or the 35 normal wedge and justifying-wedges together have been properly adjusted, it is obvious that by thus locking out one of the transfer-blocks and releasing the other the one so released can by appropriate actuating 40 mechanism be advanced and thus caused to set the stop or abutment for the mold-blade in adjusting the dimensions of the mold. A simple and efficient form of actuating mechanism will be found illustrated in Fig. 114. 45 The rear end of actuating-rod 151 is pivotally attached to one end of the actuating-lever 165, whose opposite end is pivotally connected to the frame through a compression-link 179, Fig. 7. The rear end of actuating-rod 150 is 50 in like manner connected to one end of a lever 166, whose opposite end is connected by a link 167 to lever 165 at a point intermediate its ends. The main driver or actuating lever 168 is in like manner connected by a link or 55 pitman 169 to lever 166 intermediate its ends. With this arrangement of levers when power is transmitted to lever 166 either end of the latter may become the fulcrum. Its actuating-rod 150 is locked, the end of lever 166 connected to said rod becomes the pivot end, and motion will be transmitted from the opposite end of said lever to lever 165 and from the latter to actuating-bar 151. If, on the other hand, actuating-rod 151 is locked, the lower 65 end of lever 166 becomes the pivot and motion will be transmitted from the upper end of said lever to actuating-rod 150. Thus with-

out changing the connections the motions of the main driving-lever 168 may be utilized for effecting the reciprocation of either transfer-block by the simple expedient of locking one of the two transfer-blocks against longitudinal motion, while by means of the tripping devices it can readily be determined which of the two transfer-blocks shall be locked and which brought into action. Compression-link 179 is operative at all times during the advancing movements of the transfer-blocks and affords a yielding connection when the transfer-block is seated against its limiting stop or abutment. 70 75 80 85 90 95 100 105 110 115 120 125 130

Turning now to the means for effecting the adjustments of the justifying-wedges 141 and 142. These, it will be remembered, operate in conjunction with normal wedge 132 and transfer-block 143. As will be seen by reference to Figs. 44, 51, and 52, the vertical dimensions of these wedges are but about half that of the normal wedge, and each is furnished on its underside with a series of centering and holding notches or transverse grooves corresponding in number to the columns of matrices in the die-case and to the primary controllers or pins 65 for gaging the movements of the die-case carrier. Each wedge is also provided with a head or projection 137 similar to that on the normal wedge 132. As in the case of the normal wedge, the jaws 94 95 of the secondary positioning or controlling mechanism are utilized for effecting the movements of the justifying-wedges; but inasmuch as it is only required to adjust the justifying-wedges once for each line, whereas the normal wedge is brought into action for the formation of each type, the justifying-wedges are maintained normally out of connection with the secondary positioning or gaging mechanism and are connected therewith or thrown into action only when their adjustment is desired, for which purpose controllable actuating devices are employed. The two justifying-wedges 141 142, at least those portions to which the projections 137 are applied, lie normally in a plane below wings 136, and hence entirely beyond the control of the latter, and in order to bring them within the influence of said wings it is only necessary to elevate them or either of them so that their projecting portions 137 shall stand between and within the range of motion of the two wings or jaws 136, it being understood, of course, that such elevation is to take place while the two wings or jaws are separated or opened to their fullest extent, as indicated by full lines in Fig. 58. To provide for thus connecting and disconnecting the two justifying-wedges and their adjusting devices and for accurately centering and locating them in adjusted position, the following arrangement has been devised and adopted: Pivoted on frame 146 are two levers 170 and 171, Figs. 40 and 41, each provided with two jaws 172, between which one of the justifying-wedges rests. The jaws of lever 170 are shorter than those of 171 and lie in

the plane of justifying-wedge 141, while the longer jaws of lever 171 lie in the plane of justifying-wedge 142, as clearly appears in Figs. 58 and 59. The justifying-wedges ride 5 between the jaws of their respective levers and are elevated and depressed thereby, so as to bring their heads 137 into or out of the path of wings 136. Between levers 170 and 171 and mounted in fixed position upon frame 10 is a centering-bar 173, with which the centering-notches on the under sides of the two justifying-wedges coöperate when said wedges are moved to adjusted position for accurately centering and holding said wedges. 15 The lower jaws 172 of levers 170 171 are widened or extended somewhat in the direction of the length of their respective wedges in order to furnish bearing-surfaces over which the wedges may travel during adjustment, and the upper jaws project toward each other, so as to stand above centering-bar 173, whereby the proper centering and locking of the justifying-wedges after preliminary adjustment is insured. 20

25 The controllable mechanism for effecting the adjustment of the justifying-wedges is similar to that employed for operating the pivoted trip 160. Each lever 170 171 is provided with a retracting-spring 174, which operates to hold the lever in such position that the jaws will depress and hold its justifying-wedge down out of the path of its adjusting devices, and each lever is also provided with a pivoted trip 175, whose upper end is shouldered or provided with an adjusting-nut and projects through a slot in lever 58 in position to be engaged by the higher stepped surface when in one position of adjustment or at one end of the slot and to be unaffected by said 30 lever 58 when at the other end of the slot. A spring 176, connected to the pivoted trip 175, serves to hold the latter at one extremity of the slot in lever 58—that is, away from the higher stepped surface. A trip-lever 163 and 35 plunger 164, similar to those employed for actuating the trip of the locking-pin 152, are connected to each pivoted trip 175 to throw the latter into engagement with the elevating portion of lever 58. When it is desired to 40 bring either of the justifying-wedges 141 142 within the influence of wings 136, it is only necessary to actuate the plunger 164 controlling the trip belonging to that one of the levers 170 171 which carries the selected justifying-wedge, whereupon the pivoted trip 175 will be thrown into operative engagement with lever 58, so that as the latter rises it will tilt lever 170 or 171, and the justifying-wedge lying between the jaws of the lever so tilted 45 will be raised out of engagement with centering-bar 173 and its head or lug 137 be brought into position between wings 136, and as the latter are brought together upon the secondary controller the justifying-wedge will be shifted to the desired extent, after which and as lever 58 descends the pivoted trip 175 will be disengaged from said lever and the read-

justed justifying-wedge again deposited and held upon the centering-bar 173.

The trip-levers controlling the actuating devices for the two justifying-wedges are each provided with a wing or projection 177, Figs. 22 and 56, in rear of and overlapping a portion of the trip-lever for locking-rod 152, so that whenever one of the justifying-wedge trip-levers is 5 operated to throw its pivoted trip into engagement with lifting-lever 58 it will also carry the pivoted trip 160 of locking-rod 152 into engagement with said lever 58, and thus cause said locking-rod to be elevated into engagement with the actuating-rod of the lower transfer-block 133. The purpose of this arrangement is to hold the justifying-wedges together in close contact while being set to position, so that no opportunity will be afforded for a film or layer of oil to form on their engaging surfaces, as would be the case if they were separated. By causing transfer-block 143 to be brought into action when the justifying-wedges are being adjusted the latter are set against the pressure of spring 144 and are brought accurately to position, where they remain during the formation of the line, being brought into action only when a space-type is to be made, involving the use 85 of the transfer-block 143.

From the foregoing detailed descriptions of the normal mold adjusting and justifying mechanisms it will be apparent how the mold-blade may be set or adjusted to produce any 100 desired width of type-body within the range of the normal and justifying devices. The character-types and normal spaces being separated into fifteen groups or series having a uniform ratio of increase and each group or 105 series of the same width being represented by one position of adjustment of the normal wedge, it is only necessary that the latter should be set to that one of its fifteen positions of adjustment which corresponds with 110 the selected group or series in order to form a mold-cavity of the proper dimensions. The same is true of the justifying-wedges, with the exception that each of said wedges represents a different ratio of increase, justifying-wedge 141 producing a ratio of increase for 115 each of its fifteen positions of adjustment equal to .0005 of an inch, while justifying-wedge 142 effects a ratio of increase for each position of adjustment equal to .0075 of an 120 inch.

The American system employs fifteen body sizes, with a uniform increase of one unit; but the English system has but thirteen body sizes, twelve of which represent uniform increments of one unit each, while the thirteenth represents a two-unit increase.

To adapt the present machine to the English or analogous systems presenting other than regular variations in body sizes, it is only 130 necessary to slightly modify the form of the normal wedge to correspond with the particular system. Such a modification is illustrated in Figs. 60, 60^a, 61, and 61^a. Here instead of

a uniform taper the normal wedge 132* is stepped to represent the thirteen different sizes of type-matrices arranged in the fifteen columns of the die-case. Although the ratio of increase is one unit for the first thirteen sizes, beginning with the smallest, the number of different type belonging to each series—that is, type of the same width—is not uniform, there being a larger proportion in one series than in any of the others. In the example illustrated the size of the type in units is marked upon the normal wedge at each of its fifteen positions of adjustment, the size being expressed in units. The smallest type of this series corresponding to the first column in the die-case is five units in width, the next six units, and so on up to the sixth column. As there happen to be more than fifteen type in this division, three columns (the sixth, seventh, and eighth) are assigned to the ten-unit type. The ninth column contains the eleven-unit type and so on up to the fourteenth column, containing sixteen-unit type, the sizes increasing regularly by one unit. At this point a two-unit increase takes place—from sixteen to eighteen units, the latter represented by the last column in the die-case. The figures here given are by way of illustration only, as different fonts and faces require different normal wedges, and the same is true as applied to the American system. To accommodate the larger group of ten-unit type and distribute them between the sixth, seventh, and eighth columns, the face of the wedge is stepped at the corresponding positions of adjustment, so that at each of said positions its action upon the mold-blade will be the same or equal to ten units. It is also stepped at the last or fifteenth position to effect an eighteen-unit adjustment, or two units in excess of the next adjacent position. Thus the normal wedge instead of having a regular taper, whereby its uniform movements from one position of adjustment to another will represent uniform increments in body-sizes throughout the entire series of fifteen adjustments, is interrupted or broken up into several series, each representing either the same or uniformly-varying or differentially-varying adjustments, as circumstances shall require.

The stepped normal wedge, like the uniformly-tapered wedge, occupies a position intermediate the transfer-blocks and abutment-slide 129, with its stepped face next the latter, and to facilitate its adjustment and prevent the shoulders at the ends of the steps or sections from catching upon the bearing-face of the abutment-slide the following arrangement has been devised and adopted: To the shoulder on the under side of abutment-slide 129 is fitted a plate or block 400, whose outer face or that next the stepped surface of the normal wedge is furnished with a transverse rib 401 or bearing for engagement with said normal wedge. Supported within a slot in this block 400 is a flanged plate 402, the flanged

edge resting in a groove formed in the abutment-slide and engaged by springs which operate to hold said plate 402 and block 400 outward or off its seat. The outer edge or end of this plate 402 projects beyond the face of rib 401 and into a longitudinal groove or way 403 in the face of the normal wedge. During the operation of adjusting the normal wedge the latter is held away from and out of engagement with the bearing-block 400 by the action of the springs on the rear side of plate 402, said wedge riding upon the outer edge of the plate and being held thereby from contact with rib 401. The longitudinal adjustment having thus been effected and the normal wedge brought to the desired position, when the transfer-block is advanced or brought into action it will compress the springs and force plate 402 back until the surface of the wedge becomes seated against the rib 401 and through the latter operates the abutment-slide to fix the position of the mold-blade. Upon the withdrawal of the transfer-block the springs will again project plate 402 and remove the normal wedge from rib or bearing 401, so that it can be again adjusted longitudinally without interference. This modification is well adapted for use in connection with the American system by merely substituting the uniformly-tapered wedge for the stepped or variable wedge.

It may be well at this point to remark that when setting the justifying-wedges for the line through the medium of the primary controllers or pins 65 no casts are made, the metal-injecting mechanism being thrown out of action. This is effected through the medium of pivoted trips 175, as will be explained in connection with the metal-injecting mechanism. Moreover, to produce the finer adjustments of the mold-blade by means of the two justifying-wedges two complete rotations of the main driving-shaft are usually required, one for setting each justifying-wedge; but if the positions of adjustment of the two wedges coincide both may be set at the same time during a single rotation of the driving-shaft.

Having explained how the mold-blade-positioning stop or abutment 130 is set for each type-body, it only remains to be seen how the mold-blade-actuating devices are operated to discharge the type and readjust the mold for the next succeeding cast. Let it be assumed that when the parts are as represented in Fig. 44 the mold-blade lever 128 is moving outward or in a direction to cause the approach of the mold-blade toward its adjusting abutment. In doing this it acts through spring 124, the latter yielding after the mold-blade takes bearing against its abutment, thus holding the mold-blade firmly in adjusted position. The next movement of the lever is toward the mold-blade sufficiently to take pressure off spring 124, but without making contact with the head of sleeve 126. This leaves the mold-blade abutment free for readjustment and affords opportunity for the with-

drawal of the transfer-block and the shifting of the normal wedge. After a brief dwell the lever is advanced again, and, operating through sleeve 126 and spring 123, drives the 5 mold-blade forward to eject the type from the mold. The movement of the lever is now reversed, and it retracts until contact is made with collar 127, thereby withdrawing mold-blade until its outer face is slightly within 10 the mold-cavity, so as to remove it from the track of the cross-blade. The lever again advances slightly to free the mold-blade and permit the transfer-block to be brought forward into operating position, after which by 15 a continued rearward movement the mold-blade is again drawn firmly in contact with the readjusted abutment, and the mold is in condition for the formation of the next succeeding type.

20 The Metal-Injecting Mechanism.

Under this title is included not only the melting-pot, the pump for forcing the metal from the melting-pot, and the nozzle through 25 which the molten metal is injected into the mold, but also the mechanisms operating to seat the nozzle or bring it in proper communication with the nozzle-plate of the mold to operate the pump-plunger, to throw the pump-30 plunger into and out of action, and to permit the removal of the metal-injecting mechanism from operating position into one where its parts can be more readily approached for inspection, adjustment, and repair. This part 35 of the machine will best be understood by reference to Figs. 2 to 5, inclusive, and Figs. 7, 8, and 92 to 104, inclusive.

The melting-pot and its connections are all mounted upon an independent frame 180, 40 which is pivotally supported at one side upon a vertical threaded shaft 181, mounted in bearings in the main frame. Shaft 181 forms a pivotal support for frame 180, about which the latter can be swung horizontally; but as 45 such movement would be interfered with if the melting-pot and its attachments remained in the positions they occupy in operation the said pivotal shaft is threaded into frame 180 and provided with a handle whereby it can 50 be rotated to elevate or depress the frame. A lock is provided for holding the frame in working position—such, for example, as that formed by an angular tongue or projection 55 182, Fig. 97—located on the main frame in position to enter and engage a corresponding seat 183 on frame 180 when in elevated or working position. The lowering of frame 180 by means of screw 181 withdraws the seat from locking-tongue 182 and permits the frame to 60 be swung horizontally.

The melting-pot 184, instead of being mounted directly upon frame 180, is pivotally attached to a series of arms 185, forming part of a set of parallel-motion links. These arms 65 are secured to parallel shafts 186, mounted in bearings on frame 180 and connected by a link 187, so that both shafts 186 and arms 185

will move in unison, and thus preserve the horizontal plane of the melting-pot during its vertical motions toward and from the mold. 70 The object of this is not alone to properly seat the nozzle, but also to prevent tilting the melting-pot, thus avoiding agitation or flowage of the fluid metal, more particularly in the passage leading to the nozzle.

75

The melting-pot is formed or provided with a passage or conduit 188, leading to the nozzle 189, the whole inclosed within a casing 190, between which and the melting-pot is a chamber for the reception of a non-conducting material, such as asbestos. It is desirable that the mold and connected parts should be protected from the influence of the heat generated in maintaining the type-metal in molten condition. Hence, aside from the question of 85 economy of fuel, it is important to so arrange the heating apparatus that it will maintain the type-metal in molten condition, both in the pot and in the passage leading to the nozzle, by a minimum expenditure of energy in 90 the form of heat. To this end a combustion-chamber 192, Figs. 96 and 99, is formed under the bottom of the metal-containing chamber 193, beneath which is arranged the burner 194, preferably of the Bunsen type. The 95 products of combustion are conducted from the combustion-chamber horizontally beneath the supply-passage 188 and vertically to a point near the nozzle, thence over a vertical deflecting-plate through a chamber above 100 supply-passage 188 and out through a side passage into the escape-pipe, a jet-pipe 196, located in said escape-pipe, facilitating the withdrawal of the products of combustion.

The cover of the melting-pot is formed in 105 sections and the space above the melting-pot is in open communication with a pipe surrounding escape-pipe 191, through which the fumes arising from the molten metal escape.

The metal-chamber 193 is provided with a 110 seat for the attachment of the pump-cylinder 198, the latter communicating directly with an opening formed in the seat at the end of the passage 188, through which the metal is forced into the nozzle. A solid piston 199 is 115 arranged in cylinder 198, and an induction-port formed in the body of the cylinder, but to one side of the piston and controlled by an inwardly-opening valve 200, admits the molten metal into the cylinder below the piston. 120

When in working position, the melting-pot is so arranged that its nozzle 189 will stand directly beneath and substantially in line with the bell-mouth 17 of nozzle-plate 16, as represented in Fig. 7. When the mold has been 125 adjusted and the matrix seated preparatory to making a cast, the nozzle must be elevated into close and accurate contact with the nozzle-plate. This movement is effected through the agency of an arm 201, secured to a rock-shaft 202 and bearing a roller 203 in contact with the melting-pot immediately in line with, but below, the nozzle, Fig. 99. This rock-shaft 202 is supported in bearings on frame 130

180 and is furnished with an arm 204, whose outer or free end is attached to a vertical rod 205, Fig. 95, the upper end of the latter passing through a bearing on frame 180 and engaging one end of a lever 206. A spring 207, interposed between frame 180 and an adjustable collar on rod 205, operates normally to turn rock-shaft 202 in a direction to cause the elevation and seating of the nozzle; but, except when a cast is to be made, the spring is not permitted to elevate the nozzle, but is held in restraint and under compression by a bar 208, acting on lever 206. This bar 208 forms a part of the pump-actuating mechanism about to be described.

The upper end of pump-cylinder 198 is furnished with seats for the reception of the bifurcated end of lever 209, Fig. 98, whose opposite end stands in line with the axis of threaded shaft 181 and is pivotally attached to a swivel 210, carried by a bracket on sleeve 211. The piston 199 is connected by a link 214 to the outer end of lever 215, extending substantially parallel with lever 209 and attached to the latter at or about the middle of its length by a link 216. The inner or power end of lever 215 is attached to a swivel 217, carried by cross-head 208 in line with shaft 181. The object in thus bringing the supports for the inner ends of levers 209 and 215 in axial alinement with shaft 181 is to accommodate the actuating devices to the swinging motion of the melting-pot about said shaft. Sleeve 211, to which lever 209 is connected, extends vertically through bearings in the frame, and the bar or cross-head 208, to which lever 215 is connected, is secured to the upper end of a shaft 212, passing longitudinally through sleeve 211. A shouldered pin 213, secured to the frame and extending vertically through brackets on sleeve 211 and cross-head 208, serves to limit the vertical movement of sleeve 211 and to prevent rotation of cross-head 208, while a spring 218, surrounding the lower portion of sleeve 211 and interposed between a shoulder thereon and the frame, operates in a direction to elevate said sleeve. The lower end of shaft 212 is engaged by one arm of a bell-crank lever 219, whose other arm is connected through a compression-link or elastic connection 220 with controllable actuating devices governing the operation of the pump and the elevation of the nozzle.

Bearing in mind that the elevation of the melting-pot and the seating of the nozzle are effected by the action of spring 207 and that the latter is held in check or under restraint by cross-head 208, the object in connecting the pump-actuating devices to the cylinder as well as the piston will be understood.

The throw of the piston when operated to drive the metal into the mold is in a direction opposite to that of the spring holding the nozzle in contact with the nozzle-plate, hence would tend to unseat the nozzle. This is avoided by attaching one of the pair of levers

209 215 to the cylinder and the other to the piston and connecting the levers together, as by link 216, in such manner that the pressure exerted in effecting the stroke of the pump will be distributed equally between the piston and cylinder and be exerted in opposite directions—that is to say, the power exerted at the load end of lever 215 to drive the piston down will be opposed by an equal force exerted by the load end of lever 209 tending to raise the cylinder. By this means the pump action is neutralized in so far as it might otherwise tend to disturb the position of the melting-pot or withdraw the nozzle from its seat, and it can be rendered both quick and powerful, desirable conditions in machines for casting type.

To accommodate the pump-operating devices to the different positions occupied by the melting-pot as the nozzle is alternately elevated to casting position and withdrawn therefrom, the power ends of the levers 209 and 215 are moved vertically in unison with the melting-pot and are separated only when the nozzle has been seated in the nozzle-plate and is held thereto by the full power of its elevating-spring. This is accomplished by attaching the inner or power end of lever 215 to the cross-head 208, which controls the movements of the nozzle, and the inner or power end of lever 209 to sleeve 211. Motion is communicated to cross-head 208 through shaft 212, and inasmuch as sleeve 211 is held by its spring 218 in contact with said cross-head it follows that the elevation of cross-head 208 and lever 215 will be accompanied by a corresponding movement of sleeve 211 and lever 209, thereby maintaining the parallelism of said levers 215 and 209. This relation is preserved until the nozzle is seated and cross-head 208 rises above lever 206, at which time sleeve 211 contacts with pin 213 and is arrested, while cross-head 208, continuing to rise, effects the stroke of the piston.

The controllable actuating devices for the pump serve as a means for connecting and disconnecting the metal-injecting mechanism with the driving-shaft, and they or an equivalent thereof are required in order that the action of the injecting mechanism may be suspended at intervals—as, for example, while setting the justifying-wedges or when for any purpose it becomes necessary or desirable to operate the machine without making casts.

In the present form of embodiment the pump-actuating lever 221, which derives its motions directly from the driving-cams, is connected by a link 222, Figs. 7, 101, and 104, to an arm 223, carried by rock-shaft 224, the latter supported in bearings on the main frame. Arm 223 reciprocates in unison with lever 221, and it is provided with an angular head or shoulder 225 for engagement with a latch 226, the latter pivoted in the outer end of an arm 227. This arm is carried by a sleeve 228, surrounding rock-shaft 224, and is provided with another arm 229, to which com-

pression-link 220 is connected. When latch 226 is in engagement with the angular head 225 of arm 223, as represented in Fig. 104, said head 225 will be so held between the latch and the end of arm 227 that the movements derived from driving-lever 221 will be communicated, through arm 227, sleeve 228, arm 229, and link 220, to the metal-injecting mechanism, or, in other words, the pump-actuating mechanism will be connected up for operation. To disconnect the actuating devices, and thus throw the pump out of action, it is only necessary to raise latch 226, and to effect this automatically the following arrangement has been adopted: Extending in a plane parallel with latch 226 is a tripping-arm 230, whose sleeve 231 is loosely supported upon a shaft 232, the latter being supported in bearings upon the frame, so as to permit longitudinal motion therein. Sleeve 231 is furnished with a second arm 233, carrying a spring-operated plunger 234 in position to engage a lug on the frame, said lug containing a recess for the reception of the end of the plunger when the sleeve is moved longitudinally of its axis into operative position. Arm 233 is also provided with a pin 235 for receiving the hooked end of a rod or link 236, whose opposite end is attached to the main driver or actuating-lever 168 of the transfer-blocks. During each rotation of the driving-shaft tripping-arm 230 will thus be given a complete reciprocation, its periods of rest and movement coinciding with those of the transfer-blocks. On the side of latch 226 facing the tripping-arm 230 is arranged a spring-projected pin 237, and the upper surface of tripping-arm 230 is slightly curved or so disposed relative to the latch that when the former is in its lower position it will stand below the plane of pin 237. When in normal position, tripping-arm 230 stands just beyond the plane of motion of pin 237, Fig. 101, hence does not contact with the latter; but if said tripping-arm is shifted into the plane of the pin and is then elevated it will by engagement with said pin 237 raise the latch 226 out of engagement with arm 223, as indicated by dotted lines in Fig. 104, thereby disconnecting said arm from the pump-actuating devices and holding the latter out of action while the movements of arm 223 are completed. Upon the withdrawal of the tripping-arm the connection will be re-established.

To effect the disengagement and reengagement of the pump-actuating devices by a longitudinal movement of shaft 232, the latter is furnished with a shoulder on one side of sleeve 231 and a spring 238 on the other, said spring operating to hold the sleeve over against the shoulder, the latter in the present instance being formed by reducing the diameter of that portion of the shaft on which the sleeve is mounted. Interposed between a head on the end of shaft 232 and the frame is another spring 239, the latter surrounding the larger diameter of shaft 232 and operating to move

said shaft longitudinally in a direction to carry tripping-arm 230 away from the latch and to hold it in contact with the lower ends 70 of levers 170 and 171, which operate upon the justifying devices to bring them into operative connection with their adjusting mechanism. From this arrangement it will be seen that when either of the levers 170 171 is operated to adjust its justifying-wedge shaft 232 will be moved longitudinally in a direction to bring tripping-arm 230 beneath and in the path of pin 237 on latch 226, thereby arresting the pump by disconnecting its actuating devices. In the present machine the timing of the mechanisms is such that levers 170 171 retract before the tripping-arm 230 completes its movement. Hence means for locking said arm against lateral displacement 85 while in engagement with the latch are provided. This function is performed by plunger 234, carried by arm 233, which as the sleeve is rotated to lift latch 226 is brought into engagement with the seat in its lug on the frame, 90 thereby holding the sleeve against longitudinal motion after levers 170 171 have retracted and until said plunger is withdrawn during the reverse motion of the sleeve, when spring 239 restores the sleeve to normal position with 95 its lifting-arm removed from the latch.

As it is sometimes necessary or desirable to disconnect the pump independently of the levers 170 171, the tripping-arm instead of being secured to shaft 232, as it might otherwise 100 be, is permitted longitudinal movement thereon against the tension of spring 238, and a rod 240, extending through to the front of the machine and provided with a head or lateral extension 241 in rear of a wing or shoulder 105 242 on sleeve 231, furnishes a medium whereby said sleeve 231 can be moved against the tension of spring 238 to bring its tripping-arm 230 in position to engage latch 226.

To avoid accidents and permit rod 240 to 110 be pulled out at any time, the lifting-pin 237 instead of being rigid with latch 226 is movable longitudinally and held projected by a spring, so that if sleeve 231 is drawn out when its tripping-arm is in line with the pin the latter will be retracted until the tripping-arm is carried below it, when it will again be projected above the tripping-arm in position to be elevated by the latter.

It is of course understood that the pump-operating devices are brought into action to project a stream of molten metal into the mold only after the latter has been completed by the adjustment of the mold-blade and the seating of a selected matrix, and, further, that the 120 action is a very rapid and powerful one in order to fill the mold and produce good type both as to bodies and heads or faces. Hence the necessity for throwing the pump out of action when no casts are to be made, as when 125 setting the justifying-wedges. This suspension of the pump action is insured by placing the actuating devices under the direct control of the mechanism through whose movements

the adjustment of the justifying devices is effected.

The Galley Mechanism.

- 5 The office of this mechanism is to take the individual type as they are delivered complete from the mold, assemble them in line in the order of production, and transfer the justified lines of type to the galley. The mechanism for effecting these operations (best seen in Figs. 56, 57, and 66 to 91, inclusive) may for convenience of description be divided, according to the order in which they operate upon the type, into five groups, as follows: the type-carrier, the line-assembling devices, the line-carrying devices, the line-transferring devices, and the trip mechanism for stopping the machine in the event an unjustified line should be presented to the galley.
- 20 *The type-carrier.*—It will be remembered that after the cast is made cross-blade 3 is moved to uncover the side of the mold and cut off the jet, after which the mold-blade 4 is advanced slightly to drive the type out of the mold. The type so ejected is delivered to the type-carrier 245 and by it transferred into position to enter the line-channel. This type-carrier (shown detached in Figs. 66 and 67) is arranged in the line of communication between the cross-blade and its actuating-lever 246, the latter being connected through link 247 to one end of type-carrier. The opposite end of the type-carrier is provided with a vertical hooked portion 248, engaging a corresponding but reversed hook on the cross-blade, (see Figs. 21, 56, and 57,) a form of connection which permits the ready removal of the cross-blade and at the same time insures the desired correspondence in movement between the cross-blade and type-carrier.

It is desirable in order to shorten the stroke of the type-carrier and prevent interference between it and the die-case-centering mechanism that the type-carrier should be given a limited degree of vertical motion, so that its type receiving and holding devices may be brought up opposite the mold and after receiving the type be carried downward again out of the way of the die-centering mechanism and into the plane of the type-channel. To effect this, the type-carrier is provided with a diagonal rib or projection 249, Fig. 66, which rides in an inclined groove or way formed in the front vertical wall of the recess 55 in the frame for the reception of said carrier, as indicated in Fig. 3.

In the end of the type-carrier nearest the cross-blade is located the type-holder, which latter includes the slotted head 250, provided with a type opening or channel extending transversely through the end of said carrier, and a clamping member 251, Fig. 69, movable across the channel in head 250 and co-operating with one wall thereof in receiving and clamping the type as it is ejected from the mold. The clamping member 251 is supported in guides within the type-carrier and is held

normally forward or toward the opposing clamping-surface by a spring 252. A lug or projection 253 on the clamping member 251 rides in an inclined groove 254 in the frame, the angle of inclination corresponding with that of rib 249 on the type-carrier. Said groove 254 terminates at such point in the movement of the type-carrier toward the mold that it will by its engagement with lug 253 arrest the movement of clamping member 254 just before the channel in head 250 is brought opposite the mold-cavity, thereby opening the passage for the admission of the type. Upon the return motion of the type-carrier after the type has been inserted between the clamping member 251 and the opposite face of the opening or channel in the carrier the clamp 251 will remain stationary until engaged by the type, when it, too, will be moved, thereby clamping and holding the type securely in position while being transported from the mold to the type-channel. As this action would leave the type unsupported at the time of its delivery by the mold-blade, the carrier is furnished with a type-support 255. This consists of a spring-tongue whose outer or free end rests and is guided in the clamping member 251, while the opposite or rear end is secured to a slide 251*, supported in ways and movable longitudinally of the carrier. Slide 251* is furnished with two shoulders, between which is received a block 256, carrying a headed pin, the latter extending through the shoulder on slide 251* and provided with a spring 257, interposed between the head of the pin and the slide. This spring tends at all times to hold block 256 against the shoulder on slide 251*, through which the pin passes. A lever 258, Figs. 57 and 67, mounted on the type-carrier and provided with a roller on its outer end, has its inner end in engagement with block 256. The outer end of lever 258 extends between two fixed abutments on the frame, Fig. 56, so located and arranged that as the type-carrier approaches the mold the lever will engage one of said abutments and be turned in a direction to advance the type-support 255 so that its end will be projected across the channel in the type-carrier. While it occupies this position, the type is delivered to the type-carrier, the mold-blade forcing the flexible type-supporting blade 255 back until the type is fully entered between the clamping-surfaces. While the type is thus held between support 255 and the mold-blade, the type-carrier is retracted or moved toward the line-channel, and as the type passes beyond the mold-blade it is firmly grasped and held by clamping member 251, the movement of the type-carrier withdrawing the lug 253 from its engagement with the end wall of the slot and permitting spring 252 to advance clamping member 251 toward the opposite clamping-surface, and thus grip the type lying between. As the type-carrier nears the end of its movements toward the line-channel lever 258 con-

taets with the opposite abutment and is turned in a direction to withdraw the type-support 255 out of the way, so that the type may be pushed out of the type-carrier into the line-channel.

5 *The line-assembling mechanism.*—This includes the devices for removing the type from the type-carrier and holding them in position until all the types which are to compose a line 10 have been assembled.

When at the outer extreme of its movement—that farthest from the mold—the type-carrier stands with its slot or channel opposite the entrance to the line-channel and in 15 line with the ejector-blade 259, (shown detached in Fig. 65,) which latter reciprocates through the type-carrier and delivers the type held therein to the line-channel. The rear end of this blade is attached to one arm of a bell-crank lever 331, Fig. 22, the other arm being connected through a compression-link 20 332 with the actuating-lever 333. Bevel-shoulders on ejector engage bevels on type-carrier to insure entrance without requiring exact 25 register to meet line-channel.

The present machine being designed to deal with different sizes of type, the delivery of the type from the type-carrier to the line-channel by means of an ejector-blade working through 30 the type-carrier is a matter of some difficulty owing to the fact that provision must be made for supporting the type at all times and for dealing with small as well as large type-bodies.

35 The support for the type is furnished by the spring-actuated clamp of the type-carrier, which is competent to deal with all sizes of type; but the ejector-blade 259, whose end is required to pass between the clamping-surfaces, must be as narrow as the narrowest 40 kind of type with which it has to deal. Hence it becomes necessary to make special provision for insuring its proper entrance between the clamping-surfaces and this, too, without requiring exact register between the channel 45 in the type-carrier and the line-channel. To this end a spring-pressed guide 260, Figs. 57 and 70, is arranged to press and hold the ejector-blade in contact with the face of its guiding-way nearest the mold, so that it will along 50 ways enter on the side of the type-channel formed by the movable clamping jaw or member 251.

The ejector-blade is flanged along its upper and lower edges, said flanged portions riding 55 in grooves formed in opposite walls of the type-channel, extending beyond the engaging face or end of the blade, where they are notched to admit the type, and are beveled on their outer surfaces, so that by their engagement with bevels on the type-carrier they will 60 act as guides for directing the ejector-blade into the type-channel formed between the clamping-surfaces. In the event no type is contained in the type-carrier these bevels will 65 serve to open the type-channel by forcing back the movable clamping-surface 251, so that the blade can pass it.

What is herein designated as the "line-channel" comprises a horizontal table or supporting-plate 261 and two vertical sustaining-walls, such as are formed in part by blocks 262 and 263. The block 262, Fig. 82, forming part of the wall nearest the mold, is preferably, though not necessarily, provided with a spring 264, extending longitudinally of said 70 block and having its outer end curved backwardly and overlapping the beveled end of said block. (See Figs. 76, 77, 82, and 83.) The opposite wall or block 263, Figs. 75 and 80 83, is provided with two yielding surfaces, 85 the one formed by a spring 265, sustained in position by a plate 266 and having its outer or free end bent around said plate and terminating within the line-channel, while the other one 267 is bifurcated at one end and extends on opposite sides of spring 265 lengthwise of the line-channel, the inner end being guided by a pin 268, playing in a slot formed in the tail of spring 265, as clearly seen in Figs. 75, 76, and 77. Upon reference to Fig. 90 66 it will be seen that the walls of the slot or passage in the type-carrier are cut away horizontally and that the face or engaging end of the clamping member 251 is likewise slotted. This is done to permit the outer ends or faces 95 of springs 264 265 to enter within the type-passage in the type-carrier as the latter is retracted to deliver the type therein. Springs 264 and 265 at the entrance to the line-channel constitute flexible jaws between which 100 the type are delivered, said jaws opening or yielding readily to the entrance of the type between them, but offering resistance to their withdrawal, thereby insuring the retention of the type when advanced by the ejector-blade 259. As type accumulate in the line-channel they are forced back and sustained by the pressure of spring 267, the forward end of the latter overlapping spring 265, so that 105 the type are at all times retained in proper position, for as the line is pushed toward and beyond the rear end of spring 267 it is engaged by the line-supporting blade 269, Fig. 88, which latter, as it forms a connecting-link between the line-assembling and line-carrying devices, will be explained in connection 110 with the latter.

Immediately in rear of the block 262 is arranged the galley 270, the entrance to which is closed by a vertically-movable blade 271, 120 whose outer surface is in line with and forms a continuation of that wall of the line-channel of which block 262 forms a portion. Pivoted in bearings on the frame (it may here be remarked that the galley mechanism is 125 mounted upon a frame detachably secured to the main frame) beneath and parallel with blade 271 is a lever 272, Fig. 74, the upper portion of which is provided with a grooved bar 273, lying opposite and parallel with 130 blade 271. When in normal position, the face of this bar 273 is in line with the inner ends of spring 267, so that it may be said that bar 273 and blade 271 constitute in effect parts

of the line-channel, the bottom of which is formed by a plate 261, extending horizontally beneath both of these members, as indicated in Fig. 86. The line-supporting blade 269 is 5 guided to reciprocate upon the face of bar 273, to which end it is provided with a dovetail fitting the groove in said bar, and is furnished with one or more springs 274, bearing against the wall of the groove and serving to 10 create frictional resistance to the movement of the blade. The end of the line-supporting blade 269 nearest the type is notched, as shown, for a purpose to be explained. It will suffice for the present to state that the 15 line-supporting blade is engaged by the type as they emerge from between spring 267 and the opposite wall and is pushed back as type accumulate and by the action of the line-carrier in shifting the line to a position in front 20 of the galley, which is the operation performed after all the type composing a line have been delivered into the line-channel.

The line-carrier.—This includes, in addition to the line-channel and the line-supporting blade, a pair of arms 275, Fig. 81, provided at their outer ends with type-engaging shoulders or hooks, which latter are advanced beyond the last type of the completed line, then drawn outward to bring the completed 25 line opposite the entrance to the galley, and after the line has been transferred to the galley the arms of the line-carrier are withdrawn from the line-channel in which the next line is being set up and carried to a position beyond 30 that to which the type is advanced by the ejector-blade 259, preparatory to engaging the next line when completed. The means for effecting these movements of the line-carrier or arms 275 and for returning the 35 line-supporting blade 269 after the transfer of the line to the galley will now be described.

In the frame of the galley mechanism, beneath and parallel with bar 273 of lever 272, are formed two parallel guides or ways 276 and 277, Figs. 89 and 90. In the lower of these two guides is mounted a slide 278, Fig. 84, provided with a vertical socket or bearing 279, into which is fastened the axis or fulcrum-pin 280 of head 281, carrying the line-carrier 40 blades 275. This head is also provided with a lateral projection or arm 282, extending between shoulders 285 and having its end resting in a seat formed in a slide 283, the latter riding in the upper guide 277. A friction-spring 284 (shown in dotted lines, Fig. 85) operates to retard the movements of slide 278, so that when slide 283 is moved in either direction it will first act on arm 282 and move the latter into engagement with one of the 45 shoulders 285, thus oscillating head 281 to bring arms 275 of the line-carrier into or out of the plane of the line-channel, and then by the continuation of the movement of said slide 283 motion will be communicated to slide 278, the arms of the line-carrier remaining in the position to which they were brought by the initial movement of arm 282. Thus dur-

ing the outward stroke of slide 283 the hooked ends of arms 275 will be advanced across the line-channel, so as to engage the last type of 70 the completed line, and the line will be drawn forward to a position in front of the galley, when by a reversal of the direction of its movement slide 283 will cause the withdrawal of arms 275 and the return of said arms, together with their supporting-slide 278, to first position ready to engage the next succeeding line when completed. These motions of slide 283 are transmitted from the actuating-lever 286, Figs. 72 and 73, through a slide 287, riding 80 in guides or ways 276 and provided with a pin 288, the latter working in a slot in slide 283, Figs. 85, 89, and 90, so as to alternately engage opposite ends thereof when at the extremes of the movements of slide 287. A 85 screw 289 or equivalent adjustable device operates to engage slide 283 at the limit of its outward movement, and thus insure the arrest of the line-carrier with the inner faces of its hooks in line with the wall of the galley 90 in order that the end of the line shall be accurately adjusted to position. Slide 287 is connected to its actuating-lever 286 through a double-acting compression-link 290, the latter including in the present instance a rod 95 291, pivotally attached to the outer end of the lever and extending through a sleeve 292, pivotally attached to slide 287. Rod 291 is shouldered, and between said shoulder and a sleeve on the end of the rod are arranged two 100 loose collars, with an interposed spring 293. The collars engage opposite ends of the sleeve 292, so that the spring is rendered active when the rod is reciprocated in either direction.

The outward and inward motions of lever 105 286 are slightly in excess of the permissible movement of slide 283, so that the latter will be held firmly in position against a fixed abutment at each extreme of its movement. This slide 287 is also furnished with a post or vertical projection 294, Fig. 91, carrying a pivoted latch 295, whose inner or free end, held down by the spring 296, rests between shoulders on a slide 297, Figs. 87 and 89, the latter riding in the groove or way formed in the face 115 of bar 273 in line with line-supporting blade 269. Slide 297, engaging line-supporting blade 269 as the line-carrier moves inward, serves to retract said line-supporting blade after the completed line has been delivered 120 to the galley.

The line-transferring devices.—The column-forming mechanism includes the devices by which successive lines of type brought forward by the line-carrier are transferred or delivered from the line-channel into the galley. 125

As hereinbefore explained, the entrance to the galley is closed by blade 271. This blade, which forms a portion of the right or front wall of the line-channel, fits loosely the shouldered upper end of a rod 298, passing vertically through a bearing in the galley-frame and supported upon its actuating-lever 299. The blade is held from horizontal movement 130

by a steady-pin 300 and is elevated to admit the line of type to the galley, after which it descends behind the line and sustains the latter until the next succeeding line is brought forward. The completed line is pushed or advanced into the galley by the movement of the transfer-bar 273. It will be remembered that this bar is carried by a lever 272 and forms a portion of the left-hand or outer wall of the line-channel. Said lever is held normally retracted by a spring 301, Fig. 86, and is advanced toward the galley by pressure transmitted from its actuating-lever 302 through a compression-link 303. Lever 302 engages an adjustable abutment 304 for positioning bar 273, and the spring in compression-link 303 is brought into action during the forward movement of lever 302, said spring yielding in the event the forward motion of lever 272 when operated to deliver the line to the galley is arrested.

The trip mechanism.—The last of the elemental parts of the galley mechanism is the tripping device. Its primary function is that of stopping the machine in the event an unjustified line is presented to the galley.

Mounted in guides on the galley-frame is an adjustable block 305, carrying an arm 306, overlying plate 261, and forming the front wall of the galley-entrance. The adjustment referred to is one by which the width of the galley-entrance is varied to correspond with the length of the lines cast, whatever this may be. Arm 306 is provided with guides for the reception of a tripping-block 307, the latter having its surface flush with the wall of the galley-entrance and its end nearest the line-channel projecting beyond arm 306 and of proper shape and dimensions to fit within the notch formed in the end of line-supporting blade 269. If the line delivered by the line-carrier and advanced by the line-transferrer is of standard length, it will just pass between tripping-block 307 and the opposite wall of the galley-entrance; but if the line is either too long or too short tripping-block 307 will be engaged either by the type, if the line is too long, or by the line-supporting blade 209, if the line is too short, and will be forced back by the bar 273 when the latter is advanced to push the line into the galley. A lever 308, pivoted upon block 305, is connected at one end to this tripping-block 307, and its opposite end rests in contact with a wide vertical lever 309, mounted in bearings on the frame and provided with a retracting-spring 310. (See Fig. 73.) The other arm of lever 309 operates with the shouldered arm 312 of the belt-shifting lever 313, Fig. 85, and operates when in engagement with said shoulder to hold the belt-shifting lever in operating position—that is, with the belt on the fast pulley. When, however, tripping-block 307 is forced back, it will operate through lever 308 to disengage lever 309 from the shoulder on arm 312, thus permitting the belt-shifting le-

ver to be thrown so as to shift the belt onto the loose pulley and stop the machine.

The connections between the belt-shifting lever 313 and the belt-shifter 314 can best be seen in Figs. 2, 6, 72, and 73. One arm of said lever engages a rod whose opposite end is in contact with an arm on rod 315, extending from front to rear of the machine, said rod 315 being provided with a spring 316, the latter operating in a direction to throw the belt from the fast to the loose pulley except when restrained by the engagement of lever 309 with the belt-shifting lever 312.

Galley-driving mechanism.—The motions of the galley mechanism although derived, primarily, from the main driving-shaft, are communicated through a supplemental shaft 317, mounted in bearings on the galley-frame and rotated through the medium of a worm-wheel 318. This shaft carries a cam-wheel 319, provided with three operating surfaces or cams—one, a peripheral cam 320, for engaging actuating-lever 302 of the line-transferrer or pusher; a second, face-cam 321, engaging actuating-lever 299 for blade 271, and a third, a grooved or face cam 322, engaging actuating-lever 286 of the line-carrier. The cam-wheel 319 is loose on its shaft and is connected therewith for operation by means of a ratchet-wheel 323, keyed to the shaft, and a spring-actuated pawl 324, carried by cam-wheel 319, thus forming a clutch or detachable connection between the shaft and cam-wheel. The pawl 324 is provided with an angular shoulder or arm 325 and a beveled pin 326 and is held normally from engagement with ratchet-wheel 323 by an intercepting and arresting lever 327, the latter pivotally supported on a vertical post on the galley-frame and having its opposite end standing in line with shaft 232 of the pump-actuating mechanism, so that when said shaft 232 is moved longitudinally by shifting-levers 170 171 to throw the pump out of action the same movement will throw lever 327 out of engagement with pawl 324, and thus start the galley mechanism in motion. The angular shoulder 325 of pawl 324 is received and held between a fixed shoulder 328 on lever 327 and a vertically-movable shoulder formed by a latch 329, pivotally connected to said lever 327. The instant pawl 324 is released by the withdrawal of lever 327 it flies into engagement with its ratchet-wheel, and in so doing its angular shoulder 325 passes beyond the engaging face of fixed shoulder 328 on lever 329, so that it cannot be reengaged thereby should lever 327 be released before the pawl is carried beyond its path. The withdrawal of lever 327 is followed by its return to normal position under the action of spring 330, which position is one lying in the path of movement of the angular shoulder 325, so that when the cam 319, carrying said pawl, shall have made a complete revolution the pawl will be engaged by the fixed shoulder 328 on lever 327, thereby withdrawing the

pawl from its ratchet-wheel and arresting the motion of cam-wheel 319. In doing this the beveled pin 326 on pawl 324 by its engagement with latch 329 will lift the latter and 5 pass beyond it, whereupon said latch will resume its position behind shoulder 325 and retain the latter in position.

It may here be mentioned that the galley-actuating devices are protected by a detachable cover-plate 311. (Seen only in Fig. 1, it being omitted in the other views in order to disclose the mechanism beneath.)

From the foregoing description it will appear that the controllable members of the 15 galley mechanism or those through which its movements are inaugurated are actuated to set the mechanism in motion by the same devices that are employed for setting the justifying mechanism for the next succeeding line, 20 thus dispensing with one useless rotation of the driving-shaft and obviating the necessity for a separate galley perforation in the record-strip.

The Paper-Feed.

25 The office of the paper-feeding mechanism is to advance the record-strip intermittently at regular intervals, so as to bring the perforations opposite the air-ports of the pneumatic system for controlling the various operations of the machine. In its general features it resembles that heretofore employed for the same purpose and differs therefrom mainly with respect to the actuating devices. The details of this mechanism are best seen in Figs. 105 to 110, inclusive. The devices comprising this part of the machine are mounted upon a frame separable from but secured to the main frame and include supports for the winding 30 and supply spools 335 336, a rounded or semi-cylindrical cross-bar 337, pin-wheels 338, one at each end of the cross-bar, a shaft 339, carrying said pin-wheels, a pulley 340 on shaft 339, a pulley on the winding-spool, and an 35 elastic belt 341, through which motion is transmitted from pulley 340 to the winding-spool.

The cross-bar 337 is provided with a longitudinal series of ports, and above the latter operates the air-bar 342, containing an air-chamber, said air-bar being supported upon arms 343, pivoted loosely on shaft 344. This shaft is furnished with two arms 346, each of which is connected to one end of the air-bar by a rod 350, pivoted upon the air-bar and 40 passing through a lug on arm 346. A nut or shoulder on the rod above the lug forms a positive connection for raising the air-bar, while a spring 351, interposed between said lug and the air-bar, furnishes a yielding connection for depressing and seating the latter. The air-bar is normally upheld or elevated by a spring 345, engaging one of the arms 346, while the other arm carries an adjustable contact for engaging the inlet-valve 347 to open 45 the latter when the air-bar is depressed and seated upon the record-strip. The operation

of these parts, briefly stated, is as follows: The air-bar being elevated and inlet-valve closed, shaft 339 is turned sufficiently to advance the record-strip from one line of perforations to the next, in doing which the pin-wheels engage perforations in opposite edges of the record-strip and at the same time turn the winding-spool by means of the belt and pulleys, thus drawing the record-strip from the supply-spool and winding it upon the winding-spool. When a feed motion has been thus produced, the air-bar is brought down into close contact with the surface of the record-strip, and at the same time or immediately thereafter the inlet-valve is opened and air under pressure admitted within the air-bar, from whence it escapes through such of the ports in the cross-bar as are uncovered by perforations in the record-strip and passes to the various actuating or controllable members of the machine.

50 The movements of the paper-feed and air-bar are derived from the main actuating-lever 349 and are transmitted through connecting-rod 352 to lever 353, pivoted on the side of the paper-feed frame and provided with two connections, the one extending to the air-bar-actuating devices and the other to the paper-feed-actuating devices. The connection between lever 353 and the air-bar-actuating devices is, through a link 354, provided with a slotted head open at one side for the entrance and engagement of pin 348 on arm 346, a spring 355 serving to hold the link in 55 engaging position, at the same time permitting it to be withdrawn when desired.

Upon one end of shaft 339 is secured a ratchet-wheel 356, and surrounding the latter and concentric therewith is an annulus 357, 60 provided with a lug 358, located between adjustable limiting-stops 359. This annulus is permitted a limited movement around the ratchet-wheel 356, (the extent of such movement being governed by the position of the stops 359,) and upon it is pivoted a three-armed pawl 360, one branch being furnished with an angular engaging portion adapted to enter between the teeth of the ratchet-wheel, the second branch on the opposite side of the 65 pivot riding in a curved recess or slot in the outer end of a locking-pawl 361, the latter pivotally supported on the frame, while the third or intermediate branch is connected to lever 353 through a compression-link 362, the latter yielding on the downward stroke of lever 353. When the load end of lever 353 is elevated, it will operate first upon pawl 360, tilting the latter in a direction to withdraw 70 its engaging point from the ratchet-wheel, at the same time throwing the locking-pawl 361 into engagement therewith through the medium of the arm riding in the slot in said locking-pawl, thus locking shaft 339 against rotation, after which the motion is transmitted 75 to the annulus or support 357 and the pawl is retracted until arrested by the engagement

of lug 358 with stop 359. Upon the reversal of the movement of lever 353 locking-pawl 361 will be withdrawn from the ratchet-wheel, and simultaneously therewith the engaging end of pawl 360 will be brought into engagement with said wheel 356, after which the motion will be communicated to the supporting-annulus and shaft 339 will be turned until the movement is arrested by the contact of lug 358 with the opposite stop 359. A reversal of the movements will cause the reengagement of locking-pawl 361 and the disengagement of pawl 360, as before explained.

A cam-lever 363, pivoted upon the frame above locking-pawl 361 in position to engage the latter, may when desired be employed to hold the locking-pawl in engagement with the ratchet-wheel 356, and thus prevent the movement of the pin-wheel shaft 339, connection 362 yielding in such case during the throw of lever 353.

As it is sometimes desirable to start up the machine with the paper-feed mechanism inactive or to arrest the action of the latter while the machine is in motion, an uncoupling device has been interposed between actuating-lever 349 and lever 353, as indicated in Fig. 106. The lower end of connecting-rod 352 is provided with a bifurcated head 364, the arms of which are slotted for the reception of pin 365, carried by actuating-lever 349. Pivoted upon this pin 365, between the arms of head 364, is a block 366, adapted when swung into position to occupy the space between pin 365 and head 364, so that said head and its connecting-rod will move in unison with actuating-lever 349. A spring-actuated latch 367 serves to hold block 366 in position. To disengage actuating-lever 349 from connecting-rod 352, it is only necessary to press block 366 down or swing it out from between the arms of head 364, as indicated by dotted lines in Fig. 106, thus permitting pin 365 to ride freely in the slots formed in the arms of head 364. Each spool is mounted upon a removable pin supported in bearings in the frame, so that it can be withdrawn for the removal and insertion of the spools, the pin for the winding-spool passing through the pulley and carrying a feather or equivalent device for locking the pulley and spool so that they will be rotated together.

The supply-spool is usually furnished with permanent flanges or heads; but the winding-spool is provided with one head only, (in order that the strip after use may be readily slipped off without unwinding it,) the other head being mounted in bearings in the frame, as shown in Fig. 110.

60   *The Driving Mechanism.*

Thus far in describing the various mechanisms the several movable parts have been in most instances traced back only to their actuating-levers, it being presumed that suitable and properly timed and connected driv-

ing mechanism for giving to the several actuating-levers their proper motions was supplied. The special and preferred arrangement and the approximate forms of the cams 70 are illustrated in Figs. 32 and 113 to 122, inclusive.

Although grooved or other known forms of cams might be employed for giving motion to the several actuating-levers, the preferred arrangement is one in which a pair of cams acting in opposition are employed for each actuating-lever, one of said cams effecting the motions in one direction and the other in the opposite direction and both acting upon a roller carried by the lever between the opposing surfaces of the cams. By this means the wearing-surfaces are preserved, as the motion of the roller instead of being alternately in opposite directions is continuously 85 in the same direction, although varying in speed. The two sets of cams are mounted upon parallel shafts 370 371, supported in bearings on the side of the main frame and connected through a train of gears 372 to operate in the same direction and at the same rate of speed, Figs. 1 to 6, inclusive. The fast and loose pulleys 373 are mounted upon one of these shafts 370, and the intermediate gear in the train of gears 372 carries a worm 95 374, Fig. 6, in engagement with worm-wheel 318 of the galley-driving mechanism. As matter of convenience and adaptation the several actuating-levers are arranged in two series, each provided with its own shaft or fulcrum, 100 Fig. 6. By reference to Figs. 1 and 113 it will be seen that the lower or power ends of the actuating-levers extend down between driving-shafts 370 371 in line with their respective pairs of cams, and beginning at the left these 105 are the pair of cams 377, Fig. 115, operating upon the actuating-lever 333 for ejector-blade 259; cams 378, Fig. 32, and actuating-lever 178 for advancing and retracting the mold-blade 4; cams 379, Fig. 122, and actuating-lever 349 of the paper-feed; cams 380, Fig. 121, for actuating-lever 78 of die-centering mechanism, connected through main actuating-lever 390 and compression-link 391, Figs. 2, 6, and 22; cams 381, Fig. 120, and actuating-lever 58 for die-centering plunger; cams 382, Fig. 119, and actuating-lever 168 for transfer-wedges; cams 383, Fig. 118, and actuating-lever 221 for pump mechanism, and cams 384, Fig. 117, and actuating-lever 246 120 for type-carrier. The relative positions of adjustment of these several cams upon the two driving-shafts are indicated by the grooves for receiving the keys. The bell-crank 88, Fig. 33, operating the locking-bolts 86 of the secondary controller for the die-case-centering mechanism, is caused to operate in unison with the actuating-lever 58 of the centering-plunger to unlock said controllers as the centering-plunger enters its seat in the matrix-block by having the power-arm of its actuating lever 392 connected to the power-arm of lever

125

130

58, the load end of said lever being connected to bell-crank 88 through rod 393.

The Pneumatic System.

- 5 From the foregoing description of the several mechanisms, separately considered, it must be plain that all that is required to complete the machine and render its several parts coöperative and responsive to the will of the 10 operative who prepares the record-strip is a competent system of communication between the perforated record-strip and the several controllable members of the die-case-centering mechanism, the justifying-wedges, and the transfer-blocks. This function is performed by what is herein termed the "pneumatic system" or series of air tubes or passages 385, through which communication is established between the parts in the cross-bar 20 and the pistons 66 of the primary controllers 65, and those of plungers 164 operating upon the trip-levers of the justifying-wedges and the locking-rod for the transfer-blocks.

By reference to the diagram Fig. 112 it will 25 be seen that each port in the cross-bar 327 is in open communication with one of the several cylinders referred to, so that any one or more of the pistons can be operated by forming a perforation in the record-strip in 30 line with the desired pin or plunger. There being but fourteen movable stop-pins in each series of primary controllers, the omission of a perforation in the record-strip corresponding to one of them effects the interposition 35 of the fifteenth stop or fixed pin 65*, which is the equivalent of a movable pin directly controlled by a perforation in the record-strip, so that it may rightly be said that the record-strip directly controls the die-case-centering mechanism as to each of its series of 40 adjustments in transverse planes—lines and columns—through the pneumatic system.

Summary of Operation.

- 45 Having described in detail the several constituent elements of the organized machine, a brief summary of its operation will suffice.

At the commencement of each line the justifying-wedges are to be set to produce space-type that will justify or fill out the line, assuming the character-type are of normal dimensions according to the particular system of measurement adopted. It is the office of the operative who prepares the record-strip 50 to determine not only what characters and spaces shall be produced and their order, but also to ascertain and impress the ratio of increase to be given each normal space-type, in the performance of which he is aided by 55 a special machine adapted to form the required type-perforations in the record-strip and indicate the justification ratio for the spaces.

Each justifying-wedge represents fifteen 60 degrees of adjustment on a regular scale, whose increments are uniform and proportional to the taper of the wedge. Hence to

produce a mold-cavity of the desired width for the space-type it is only necessary that the justifying-wedge should be set at that 70 one of its positions of adjustment whose value plus that of the normal wedge represents the required position of the mold-blade.

The setting of each justifying-wedge involves two operations—first, for position, and, 75 second, for connection with the positioning mechanism. Position is determined through the medium of the primary controllers or stop-pins 65 of the die-case-carrier system. Consequently a perforation is made in the record-strip to designate which of the fourteen positions of adjustment represented by the movable stop-pins 65 the wedge is to occupy, or the perforation for position is omitted, in which case the maximum adjustment produced by fixed stop-pin 65* will be attained. Another perforation is required to designate the particular wedge and to place it in connection with the actuating devices for adjustment, and this is done by forming a perforation in line with the port leading to one or the other of the pistons controlling the justifying-wedge trip-lever. Thus either or both justifying-wedges are set to position and locked, and incidentally the galley mechanism is started in action to take care of the preceding line; but although adjusted for the line the justifying-wedges are inoperative to affect the position of the mold-blade and the size of the type until through the action of 80 transfer-blocks the control of the mold-blade is shifted from the normal wedge alone to the normal plus the justifying wedges. To effect this, two things are required—first, that the normal wedge should be properly adjusted 85 to harmonize with the justifying wedge or wedges in determining the position of adjustment of the mold-blade, and, second, that the normal - wedge transfer - block should be thrown out of action and the justifying-wedge 90 transfer-block thrown into action. Two, or at the most three, perforations in the record-strip are sufficient to accomplish these results. If, as is preferred, the space-matrix blocks are located in the last line in the die-case, the adjustment of the normal wedge 95 will be produced by a perforation communicating with the port leading to the primary controller or stop-pin representing the column whose width value corresponds with the 100 desired position of adjustment of the normal wedge. Should the space-matrix blocks be located in any other than the last line, another perforation corresponding to line adjustment would be required. Having thus 105 provided for setting the normal wedge, another perforation serves to bring the justifying-wedges into action, and that is one opposite the port leading to the trip-lever which controls the locking - bolt of the transfer-blocks, whereby the normal-wedge transfer-block is locked out of action and the justifying-wedge transfer-block brought into operation 110 so as to act in conjunction with the nor-

mal and justifying wedges in setting the mold-blade for a space-type.

One or two perforations, according to the position of the matrix in the die-case, suffice for locating each character-matrix and adjusting the normal wedge to correspond therewith through the medium of the two series of primary controllers pertaining to the line and column movements of the die-case.

10 The readjustments of the die-case, the normal and justifying wedges, and the mold-blade are each effected by a movement direct from the position of prior adjustment to the position of next subsequent adjustment. Thus 15 the normal or zero position is eliminated and the motions incident to the return to a zero point before advancing to the next succeeding position are entirely avoided.

The adjustments effected by the normal 20 and justifying wedges while accurate, delicate, and positive are not dependent upon rigid or inflexible connections, the wedges themselves being loosely and flexibly connected to their positioning devices, so as to avoid 25 binding and distortion and the interference due to variations in temperature. So, too, the connection between the mold-blade and its actuating and adjusting devices is of a character well adapted to prevent interference 30 by variations in temperature.

The setting of the justifying-wedges for the line, taking place, as it does, after one line is completed and before another is begun, affords an opportunity for the starting of the galley mechanism to take care of the completed 35 line, and by utilizing the devices which bring the justifying-wedges into position for readjustment to automatically start the galley mechanism not only is there a saving of time 40 effected, but the necessity of a special galley perforation is avoided.

Having now particularly described and ascertained the nature of my said invention and in what manner the same is to be performed, I 45 declare that what I claim is—

1. In an organized type-casting machine such as described, and in combination with an adjustable mold, and a movable series of dies or matrices, of a controllable centering 50 mechanism operating upon the dies or matrices to carry them directly from one position of adjustment to another without returning to a zero or normal point of departure; substantially as described.

55 2. In an organized type-casting machine such as described, provided with an adjustable mold, a movable series of dies or matrices, and mold-adjusting devices, of a controllable centering mechanism engaging the 60 series of dies or matrices and the mold-adjusting devices to transport them from one position of adjustment to another directly without returning to a normal or zero point of departure; substantially as described.

65 3. In a die or matrix centering mechanism the combination with a movable series of dies or matrices, of a positioning or adjusting

mechanism for shifting the series of dies or matrices from any one position of adjustment to another directly without returning to a 70 normal or initial point of departure; substantially as described.

4. In a type-casting machine such as described employing an adjustable mold and a series of dies or matrices adjustable with respect thereto to form different type, the combination with the mold-blade of an adjusting mechanism containing a variable factor, such as the normal wedge, automatically shifted from one position of adjustment to any other 80 without returning to a normal or zero position; substantially as described.

5. In a type-casting machine such as described, the combination of the following elements, to wit; a die or matrix case; a mold 85 provided with a movable mold-blade; a normal wedge for positioning the mold-blade; and an adjusting or centering mechanism for shifting the die-case and the normal wedge directly from one position of adjustment to 90 another without first returning to a zero or normal starting point; substantially as described.

6. In a type-casting machine provided with an automatically-adjustable mold the combination with the adjustable member or mold-blade, of abnormal adjusting devices containing a variable factor—such as the justifying-wedge—and controllable adjusting devices shifting said variable factor directly from 100 one position of adjustment to another without returning to a normal or zero position; substantially as described.

7. In a type-casting machine and in combination with the mold-blade through which 105 the size of the mold-cavity is varied, of a normal and an abnormal adjusting mechanism, operating separately or together, and each containing a variable factor, with controlling or adjusting devices for moving said variable factors directly from one position of adjustment to another without returning to a normal or zero position; substantially as described.

8. In a type-casting machine provided with 115 an automatically-adjustable mold, the combination with the adjustable member—such as the mold-blade—of an abnormal adjusting or justifying mechanism containing a plurality of variable factors—such as the justifying-wedges—and controllable adjusting devices for shifting or adjusting each of said variable factors; substantially as described.

9. In a type-casting machine such as described, the combination with the movable 125 die-case, the mold provided with an adjustable section or mold-blade, the normal wedge for determining by its position of adjustment the size of the mold-cavity, and the centering-plunger, of the following elements, to 130 wit; an adjusting or centering mechanism connected with the die-case to move the latter directly from one position of adjustment to another, said mechanism also operating

upon the normal wedge to shift it directly from one position of adjustment to another, and a lock for the normal wedge operated by the actual lever for the centering-plunger; 5 substantially as described.

10. In a type-casting machine the combination of the following elements, to wit; a movable die-case; a mold provided with an adjustable mold-blade; a normal wedge for 10 adjusting the position of the mold-blade; and a die-case centering or adjusting mechanism including a pair of oppositely-movable jaws with intercepting devices for arresting them in closed position at any point within the 15 limits of their motion toward each other, said jaws engaging both the normal wedge and translating devices connected to the die-case; substantially as described.

11. In a type-casting machine provided 20 with a movable die-case, a centering-plunger and an adjustable mold, the combination therewith of the following elements, to wit; a die-case-centering mechanism whose positioning devices are a pair of oppositely-movable 25 jaws with a controllable gage determining the closed position of said jaws; a normal wedge normally controlled as to position by said jaws; a lock for said normal wedge; a justifying-wedge normally disconnected from said 30 jaws; a lock or detent for holding the justifying-wedge in adjusted position; controllable shifting devices for temporarily connecting the justifying-wedge with the jaws of the positioning mechanism; and a mold-blade 35 abutment controlled, as to position, by the normal and justifying wedges; substantially as described.

12. In a type-casting machine provided with a movable die-case, a centering-plunger 40 and an adjustable mold; the combination therewith of the following elements, to wit; a die-case-centering mechanism whose positioning devices are a pair of oppositely-movable jaws with a controllable gage determining the 45 closed position of said jaws; a normal wedge controlled as to position by said jaws; a lock for said normal wedge; a justifying-wedge normally disconnected from said jaws; a lock or detent for holding the justifying-wedge in 50 adjusted position; controllable shifting devices for temporarily connecting the justifying-wedge with the jaws of the positioning mechanism; transfer-blocks; actuating devices for said transfer-blocks; controllable 55 locking mechanism for suspending the action of either transfer-block, thereby selecting either the normal wedge or the normal and justifying wedges for determining the size of the mold-cavity; and a mold-blade abutment 60 controlled, as to position, by the normal and justifying wedges; substantially as described.

13. In a type-casting machine provided with a movable die-case, a centering-plunger, and an adjustable mold, the combination 65 therewith of the following elements, to wit; a die-case-centering mechanism provided with a positioning mechanism containing oppo-

sitely-movable jaws and a controllable gage for determining the closed position of said jaws; a normal wedge extending between and 70 in the path of movement of said jaws; a justifying-wedge normally disconnected from the jaws of the positioning mechanism; controllable devices, such as a shifting-lever, trip, trip-lever and actuating-lever, for connecting and 75 disconnecting the justifying-wedge and the positioning mechanism; transfer-blocks; controllable mechanism for locking either transfer-block out of action; and a mold-blade abutment whose position is determined by 80 the normal or normal and justifying wedges and a transfer-block; substantially as described.

14. In a type-casting machine such as described the combination with the abutment- 85 slide for the mold-blade, of the following elements, to wit; a positioning mechanism provided with oppositely-movable jaws and a controllable gage for determining their closed position at different points in the line of their 90 motion when approaching; a normal wedge extending parallel with the direction of motion of said jaws and provided with a shoulder projecting between and in the path of the two jaws, a plurality of dissimilarly-tapered 95 justifying-wedges extending parallel with the normal wedge, each provided with a projection or shoulder adapted to be engaged by the positioning-jaws but held normally outside of the paths of said jaws; controllable 100 devices for bringing the justifying-wedges successively and temporarily into the path of the jaws and between the latter, to adjust said wedges longitudinally to any of the series of positions indicated by the controllable 105 gage; a pair of transfer blocks or wedges, extending longitudinally of the normal wedge, the one lying between the normal wedge, and the other between the normal and justifying wedges; actuating devices for reciprocating 110 the transfer-blocks; and controllable locking devices for arresting either transfer-block in inoperative position while the other is moved to operative position; substantially as described. 115

15. In a type-casting machine the combination with a mold provided with an adjustable section or mold-blade and means for automatically adjusting the latter to accord with the normal dimensions of type, of a justification 120 or abnormal adjusting mechanism comprising a plurality of separately-adjustable members, such as justifying-wedges, and means for automatically positioning said members so as to vary the normal adjustments of the 125 mold; substantially as described.

16. In a type-casting machine such as described the combination with the mold and the series of movable matrices or dies, of a mold - adjusting mechanism including a 130 stepped or irregular wedge with controllable mechanism for adjusting or positioning said wedge; substantially as described.

17. In a type-casting machine the combina-

tion of the following elements, to wit: a movable die-case; a mold provided with a movable wall or mold-blade; a die-case-centering mechanism provided with a controllable positioning mechanism; a stepped or irregular normal wedge connected to said positioning mechanism for adjustment through uniformly-spaced intervals; and an abutment-slide through which the normal wedge is caused to act upon the mold-blade in positioning the latter; substantially as described.

18. The combination in a type-casting machine such as described of the following elements, to wit: a fixed mold provided with mold-blade and cross-blade; a die-case movable horizontally for bringing different matrices or dies in alinement with the mold, and vertically, to seat the centered matrix on the mold; and a type-carrier guided to reciprocate vertically and horizontally, to receive the type from the mold and carry it laterally and downwardly out of the path of the die-case; substantially as described.

19. The combination in a type-casting machine such as described of the following elements, to wit; a fixed mold provided with a type-ejecting mold-blade and a movable front wall or cross-blade; a die-case movable in a plane transverse to the axis of the mold, for centering the matrices or dies, and parallel with the axis of the mold, to seat the centered die or matrix on the mold; and a type-carrier reciprocating in a plane inclined to the axis of the mold, whereby as it recedes from the latter it will be carried downward or away from the path of the die-case; substantially as described.

20. In a type-casting machine the combination of the following elements, to wit; a fixed mold with horizontally-reciprocating cross-blade and mold-blade ejector; a horizontally and vertically movable die-case; and a type-carrier connected to the cross-blade, but guided to reciprocate in a path inclined to that of the cross-blade, whereby the type-carrier is alternately elevated and depressed as it travels toward and from the mold; substantially as described.

21. In a type-casting machine the combination of the following elements, to wit; a fixed mold with cross-blade and ejecting mold-blade; a horizontally and vertically movable die-case; and a type-carrier mounted to reciprocate in a plane inclined to the horizon, said type-carrier being furnished with a clamping member and a yielding gate or type-supporting blade, substantially as described.

22. In an organized type-casting and composing machine such as described the combination of the following elements, to wit; a mold with movable mold-blade; a die-case with controllable centering mechanism therefor; a controllable normal adjusting mechanism for the mold-blade; a plurality of abnormal or justification adjusting devices for the mold-blade, with controllable mechanism for adjusting each of said devices; a galley mech-

anism provided with a controllable starting mechanism connected with the controllable abnormal or justification adjusting mechanism; a controlling-strip; and a transmitting system governed by the controlling-strip and operating upon the controllable members of the die-case-centering mechanism, the normal mold-adjusting mechanism, and each of the abnormal mold-blade-adjusting devices; whereby the abnormal adjusting devices may be independently adjusted to predetermined positions, and the adjustment of either will operate to start the galley mechanism; substantially as described.

23. In an organized type-casting and composing machine such as described, the combination of the following elements, to wit; a mold with movable mold-blade; a die-case with controllable centering mechanism; a controllable normal adjusting mechanism for the mold-blade; a controllable abnormal or justification adjusting mechanism for the mold-blade; a galley mechanism provided with a controllable starting and stopping mechanism connected with a controllable abnormal or justification mechanism; and a controlling system governed by a controller or record strip and operating upon the controllable members of the die-case-centering mechanism and the normal and abnormal mold-blade-adjusting mechanisms, to center the dies or matrices and adjust the mold to correspond therewith, and to set the abnormal adjusting mechanism and start the galley mechanism; substantially as described.

24. The combination in a type-casting machine such as described, of the following elements, to wit; a mold provided with an adjustable mold-blade; a movable die-case; a controllable centering mechanism for the die-case; a controllable normal adjusting mechanism for the mold-blade; a controllable abnormal mold-blade-adjusting mechanism comprising a plurality of independent adjustable elements, such as justifying-wedges; a controlling member, such as a perforated strip; and a controlling system, such as a pneumatic system, intermediate said controlling member and the controllable mechanisms mentioned, for governing the centering of the die-case, the position of the normal adjusting mechanism, and the positions of each abnormal adjusting mechanism; substantially as described.

25. In a type-casting and composing machine such as described the combination with the abnormal or justifying mechanism for the mold, and the controllable devices for setting or adjusting said mechanism, of a galley mechanism provided with a controllable driving mechanism, and connections intermediate the abnormal or justifying mechanism and the controllable member of the galley-driving mechanism for starting the latter when the abnormal or justifying mechanism is set or adjusted, substantially as described.

26. In a type-casting machine such as de-

scribed provided with a movable die-case containing a plurality of dies or matrices; a fixed mold with an adjustable member, such as a mold-blade, for varying the dimensions of the mold-cavity; normal and abnormal or justifying mold-adjusting mechanisms; and a galley mechanism provided with a controllable driving mechanism; the combination with the controllable mechanism for setting the abnormal or justifying mold-adjusting members and the controllable member of the galley-driving mechanism, of connecting mechanism for actuating the controllable member of the galley-driving mechanism to set the latter in motion when the adjustment of the abnormal or justifying mechanism is effected; whereby the setting of the justifying mechanism for a line starts the galley mechanism in action, to dispose of the previously-completed line; substantially as described.

27. In a type-casting and composing machine such as described the combination with the controllable member of the galley-driving mechanism, of actuating devices engaging said controllable member connected with and operated by the controllable adjusting mechanism of the mold-justifying devices, substantially as described, whereby the setting of the justifying mechanism connects the galley mechanism with its driving mechanism.

28. In a type-casting and composing machine such as described, the combination with the adjusting or setting mechanism of the abnormal or justifying devices, a controllable pump-actuating mechanism, and a controllable galley-actuating mechanism, of actuating devices controlled by the setting mechanism of the justifying devices and engaging the controllable members of the pump and galley-actuating mechanisms, whereby the setting of the justifying mechanism will effect a suspension of the pump action and start the galley mechanism; substantially as described.

29. In a type-casting and composing machine the combination with the starting-lever of the galley mechanism and the shifting-lever of the justifying-wedge, of a shaft interposed between said shifting-lever and starting-lever for transmitting motion from the former to the latter; substantially as described.

30. In a type-casting machine such as described the combination with a reciprocating injecting mechanism consisting of melting-pot, pump and nozzle, of a pump-actuating mechanism including opposing power-transmitting devices engaging the piston and cylinder respectively; substantially as described.

31. In a type-casting machine the combination with the mold, of a vertically-reciprocating injecting mechanism including melting-pot, pump and nozzle, and a supporting-frame pivotally attached to the main frame on a vertical axis; substantially as described.

32. In a type-casting machine such as described and in combination with the verti-

cally-movable injecting devices, including melting-pot, pump and nozzle, of a vertically-adjustable and laterally-movable supporting-frame therefor, and a lock for holding said frame from lateral motion when in elevated position, whereby the injecting mechanism can be lowered and swung from beneath the mold; substantially as described.

33. In a type-casting machine the combination with the pump and the actuating mechanism therefor, of a controllable disengaging or arresting device including a reciprocating driving member, a driven member carrying a latch for engagement with the driving member, and reciprocating member, moving in a direction to release the latch from engagement with the driving member and shiftable into and out of the path of said latch; substantially as described.

34. In an adjusting or centering mechanism for shifting a member from one to another of a series of indicated positions the combination of the following elements, to wit; a positioning or gaging mechanism provided with oppositely-movable jaws; a fixed gage composed of a plurality of stops or pins serially arranged and each adapted to be projected into the path of one of said jaws to arrest the latter as it approaches the opposite jaw; a shiftable member or gage located between the two jaws in position to be engaged by the latter as they approach; and actuating devices engaging and connecting the two jaws, to cause them to advance successively in closing upon the shiftable member, said devices including a pair of levers, the one pivotally connected to the frame and the other to the actuating-lever at points intermediate their ends, each of said levers being pivotally connected at one end to one of the jaws while their opposite ends are connected together, and a spring operating through the connected levers to hold one jaw against a stop at the outer extreme of its motion while the opposite jaw is advancing and until it contacts with the stop, when, by the continued motion of the actuating-lever, the second jaw will be advanced thus positioning the shiftable member projecting between the jaws; substantially as described.

35. In a type-casting machine the combination with the adjustable mold-blade for varying the size of the mold-cavity, its actuating devices and limiting-abutment, of a normal wedge, a justifying-wedge and a reciprocating transfer-block, substantially as described.

36. In a type-casting machine, as a means for effecting the adjustments of the mold for both normal and justifying type, the combination with the adjustable member or mold-blade, of a normal adjusting device, an abnormal adjusting device, and two interpolants or transfer-blocks operating successively, the one to throw the normal adjusting devices into operative relation with the mold-blade and the other to throw both the abnor-

mal and normal adjusting devices into operative relation with the mold-blade; substantially as described.

37. In a type-casting machine the combination with a stationary mold and a movable metal-injecting mechanism including a pump and nozzle, of two opposing connected levers, one connected to the cylinder and the other to the piston of the pump, an actuating device for each lever, and mechanism operating upon said actuating devices to move them in unison with the injecting mechanism as the latter advances toward and recedes from the mold, and to separate them and thus project the metal into the mold after the nozzle has been seated; substantially as described.

38. In a die or matrix adjusting mechanism the combination with the movable die or matrix case, and a gage or controller presenting a graduated series of stops or contacts corresponding to the various positions of adjustment of the die-case, of actuating and controlling mechanism intermediate the die-case and gage and controlled, as to position, by the latter, said actuating and controlling mechanism being moved alternately into and out of engagement with the die-case, so that in moving or setting the latter it will be carried directly from one position of adjustment to another; substantially as described.

39. The combination, to form an adjusting mechanism for a shiftable member, such as a die-case, of the following elements, to wit; a primary controller or fixed gage comprising a plurality of controllable contacts or stops serially arranged and constituting an index for the various positions of adjustment; a primary positioning mechanism controlled as to position by the primary gage; a secondary or shiftable gage controlled, as to position, by the primary positioning mechanism; a secondary positioning mechanism, controlled, as to position, by the shiftable gage; a shiftable member such as a die-case; and translating devices intermediate the secondary positioning mechanism and the shiftable member for moving the latter from one position of adjustment directly to another position of adjustment; substantially as described.

40. In a die or matrix adjusting or centering mechanism, the combination with the die-case and the controlling-gage by which the position of the die-case is determined, of a centering or adjusting mechanism independent of the die-case, and coöperating alternately with the controlling-gage and the die-case, to first set or determine the adjusting motion and then transmit or communicate the adjusting motion to the die-case, substantially as described.

41. In a die or matrix centering or adjusting mechanism the combination with a die-case movable in two directions to bring any one of the series of matrices to position at a fixed point, of two sets of positioning or adjusting devices operating independently and each acting to shift the die-case in one direc-

tion only the number of spaces or degrees necessary to bring the column or line containing the selected matrix in alinement with the centering-point, whereby the transition from one position of adjustment to another, or the shifting from one matrix to another at the centering-point, is effected directly, without a return to an initial or normal point of departure; substantially as described.

42. In a die or matrix centering or adjusting mechanism, the combination with a die-case movable in two directions on intersecting lines, to bring any one of a series of matrices to a fixed center, and two fixed gages or controllers each serving to indicate the position of the die-case within the limits of its movements in one direction, of two adjusting or centering mechanisms each operating in conjunction with one of the fixed gages or controllers and mediate or immediately upon the die-case to carry the latter in either direction from any one position of adjustment to another, whereby the centering of the matrices is performed by a direct movement from one position of adjustment to another without an intermediate return to a normal or zero starting point; substantially as described.

43. In an adjusting mechanism for a shiftable member, such as the secondary gage of the die-case-centering mechanism, the combination of the following elements, to wit; a fixed gage comprising a series of controllable stops or contacts indicating relative positions of adjustment; a positioning mechanism including a pair of oppositely-movable jaws, one of which is adapted to engage and be arrested by the fixed gage and form a stop or abutment for limiting the movement of the opposite jaw; and a shiftable member occupying a position between the jaws of the positioning mechanism; whereby the position of said shiftable member is varied to accord with that one of the stops or contacts of the fixed gage at the time operating upon the positioning mechanism; substantially as described.

44. In a die-case-centering mechanism the combination of the following elements, to wit; a shiftable gage; a positioning mechanism provided with oppositely-moving jaws adapted to close upon the shiftable gage in any position of adjustment; a shiftable die-case; and translating devices connected to the die-case and projecting between the jaws of the positioning mechanism so that in closing upon the gage the jaws will bring the die-case into a position corresponding with that of the gage; substantially as described.

45. In an adjusting or centering mechanism the combination of the following elements, to wit; a shiftable gage with means for locking it in adjusted position; a primary positioning mechanism provided with oppositely-moving jaws between which the shiftable gage is located and by which the latter is carried to position; a secondary positioning mechanism provided with oppositely-mov-

able jaws for engagement with the shiftable gage; a translating device located intermediate the jaws of the secondary positioning mechanism; and a primary gage acting upon

5 the primary positioning mechanism to determine the position of its jaws when closed; substantially as described.

46. The combination in a die or matrix centering or adjusting mechanism of the following

10 elements, to wit; a die-case movable in guides to bring successive sections in line with a fixed point or center; a translating device connected to said die-case; a positioning mechanism comprising oppositely-movable jaws between which said translating device extends and by which the die-case is carried in either direction to adjusted position; and a shiftable gage interposed between and movable in the plane of motion of the said jaws,

15 to determine by its position the point at which the two jaws shall be brought together; whereby, during the separation of the two jaws, preliminary to the resetting of the gage, the die-case is released from its actuating devices, and as the jaws are again brought together to the position indicated by the gage the die-case will be shifted; substantially as described.

47. In a matrix-centering mechanism and 20 in combination with a mold, a die-case, actuating devices for the die-case, a centering-plunger and a friction device or brake for alternately retarding and releasing the die-case; substantially as described.

35 48. In a matrix-centering mechanism the combination with a die-case, its carrier and the mold, of centering devices for the die-case and its carrier operating on intersecting lines, to center individual dies or matrices above 40 the mold; a centering-plunger; and brakes or friction devices for the die-case and its carrier, engaging the latter during their motions of translation and being withdrawn or relieved during the action of the centering-

45 plunger; substantially as described.

49. In a die-case-centering mechanism, the combination of the following elements, to wit: a die-case; a die-case carrier; a die-case centering or shifting mechanism; a die-case-carrier centering or shifting mechanism; a mold; a centering-plunger in line with the mold; a brake or friction device for the die-case applied to the connection between the die-case and its centering mechanism; and a brake or 55 friction device applied to the die-case carrier; said brake or friction devices operating during the motions of translation of the die-case and its carrier, and being suspended during the action of the centering-plunger; substantially as described.

50. In a die or matrix centering mechanism the combination of the following elements, to wit; a die-case; a die-case carrier; a supporting-frame for the die-case and its carrier;

65 independent actuating devices for the die-case and for its carrier; a centering-plunger; frictional braking devices intermediate the

die-case and its carrier; and actuating devices for reciprocating the centering-plunger and simultaneously therewith withdrawing the 70 braking devices; substantially as described.

51. In a die or matrix centering mechanism the combination with the vertically-movable supporting-frame, the die-case carrier, the die-case and the centering-plunger, of the following elements, to wit; a friction-block mounted upon the supporting-frame in position to engage the die-case carrier; an actuating device, such as a lever, for operating the friction-block; and a spring with limiting-stops interposed between the frame and the friction-block-actuating device; whereby, as the die-case-supporting frame is lowered, after the preliminary centering of the die-case, the friction-block-actuating device will be 85 withdrawn from its actuating-spring, leaving the die-case free to respond to the action of the centering-plunger; substantially as described.

52. In a die or matrix centering mechanism, the combination with the horizontally-reciprocating die-case carrier and its vertically-movable supporting-frame, of the centering-plunger; the friction-blocks mounted upon the supporting-frame in line with the guides 95 for the carrier and engaging the latter; the curved levers pivoted in the supporting-frame engaging the friction-blocks and partially encircling the centering-plunger; and the vertically-movable pins each contacting with one 100 of the levers and provided with an actuating-spring and a limiting stop or gage; substantially as described.

53. In a die or matrix centering mechanism, the combination with the supporting-frame 105 for the die-case and its carrier, and the centering-plunger, of the actuating-lever engaging the centering-plunger, and the link and lever for transmitting motion from the actuating-lever to the supporting-frame, substantially as and for the purpose set forth.

54. In a die or matrix centering mechanism the combination with the centering-plunger and the spring-sustained supporting-frame upon which the die-case is adjusted to bring 115 any matrix-block into alignment with the centering-plunger, of the actuating-lever engaging the centering-plunger, the lever connected to the supporting-frame, and a connection between said last-named lever and the actuating-lever, whereby motion in the same direction but at relatively-different speeds will be communicated to the centering-plunger and supporting-frame; substantially as described.

55. In an adjusting or centering mechanism such as described containing a primary controller or fixed gage, a primary positioning or gaging mechanism provided with oppositely-movable jaws, and a secondary controller or shiftable gage, the combination, to form an actuating mechanism for the jaws of the said positioning or gaging mechanism, of the following elements, to wit; a lever mount-

ed on a fixed fulcrum and having one end attached to one of the jaws; a second lever having one end attached to the other jaw and its opposite end connected through a link to the first-named lever; a spring operating to hold one of said levers retracted; and an actuating-lever connected to said second lever intermediate its ends; whereby, as the actuating-lever is moved in one direction, it and the spring will separate the jaws, and when moved in the opposite direction, will advance one jaw until arrested by a stop-pin of the fixed gage and then advance the opposite jaw against the resistance of the spring, thus carrying the shiftable member to a position of adjustment corresponding with the position in the series of the stop-pin in engagement with the jaw.

56. The combination with the two pairs of connected levers 73, 74, one lever of each pair being attached to a fixed pivot and the other to a reciprocating actuating device, of a spring-retractor connected to one lever of each pair, whereby the corresponding levers of each pair are advanced and continued in motion until arrested before the opposite levers are affected by the actuating device; substantially as described.

57. The combination with two positioning mechanisms each provided with a pair of oppositely-movable jaws and a fixed gage for determining the closing position of each pair of jaws, of the two sets of connected levers pivotally attached to the jaws, one lever of each set attached to a fixed pivot and the other to a reciprocating driver, and a spring-retractor engaging one lever of each set or pair, so that in the act of closing the jaws of each positioning mechanism, the jaw contacting with the fixed gage will be first advanced and when arrested motion will be communicated to the opposite jaw; substantially as described.

58. In a centering or adjusting mechanism and as a means for operating the pairs of oppositely-movable jaws of the positioning or gaging mechanisms, the combination with said jaws of a lever system for each pair of jaws comprising two levers or members pivotally connected together at one end and each attached to one of the jaws, a fixed bearing or pivot to which one of said levers or members is connected by a link attached intermediate the points of attachment to the jaw and the opposite lever or member, and an actuating device or mechanism connected to the other lever or member intermediate the points of attachment to the jaw and first-named lever or member; substantially as described.

60. 59. In a centering or positioning mechanism, as a means for actuating the jaws of the primary and secondary positioning or gaging mechanisms, the combination of the following elements, to wit; a pair of levers pivotally connected at one end and having their opposite ends connected respectively to the opposing jaws, one of said levers being furnished

with a fixed fulcrum and the other connected intermediate its ends to the actuating-lever; and a second pair of connected levers engaging the other pair of jaws, the fixed fulcrum and the connection with the actuating-lever of this second pair being reversed in position as compared with those of the first-named pair; whereby the two pairs of jaws will be caused to move in relatively opposite directions, one pair closing as the other separates or opens; substantially as described.

60. In a centering or adjusting mechanism such as described for locating the position of a movable member, such as a die-case, at any of a series of indicated positions by a two-way movement on intersecting lines, the combination with such movable member or die-case of the following elements, to wit; two fixed gages or controllers; two positioning mechanisms each provided with oppositely-movable jaws whose closed position is determined by a member of the fixed gage; a secondary or shiftable gage intermediate the jaws of each positioning mechanism; two secondary positioning mechanisms each provided with oppositely-movable jaws whose closed position is determined by the shiftable gage; and translating devices intermediate the jaws of one secondary positioning mechanism and the movable member or die-case, and between the jaws of the other secondary positioning mechanism and the carrier or support for said movable member or die-case; substantially as described.

61. In a centering or adjusting mechanism such as described, for locating the position of a movable member, such as a die-case, by movements in transverse lines, the combination of the following elements, to wit; two primary controllers or fixed gages; a primary positioning mechanism with oppositely-movable jaws coacting with each primary controller, the latter determining the closed position of said jaws; a secondary controller or shiftable gage intermediate the jaws of each primary positioning mechanism and set thereby; a lock for each secondary controller; a secondary positioning mechanism for each secondary controller provided with oppositely-movable jaws whose closed position is determined by the secondary controller; translating devices intermediate the secondary positioning mechanisms and the movable member or die-case; and actuating devices operating upon the jaws of the primary and secondary positioning mechanisms to open one set of jaws while closing the other set; substantially as described.

62. In a centering or adjusting mechanism, such as described, for locating the position of a two-way movable member, such as a die-case, the combination of the following elements, to wit; two primary controllers or fixed gages; two primary positioning or gaging mechanisms each provided with oppositely-movable jaws, whose closed positions are determined by the members of the fixed gages;

- a secondary controller or shiftable gage interposed between and located by the jaws of each primary positioning mechanism; a secondary positioning or gaging mechanism with 5 oppositely-movable jaws for each secondary controller, the latter determining the closed position of said jaws; translating devices intermediate the jaws of the two secondary positioning mechanisms and the movable member or die-case; and a single actuating-lever 10 immediately connected to the jaws of the primary and secondary positioning mechanism for opening and closing them in alternation; substantially as described.
- 15 63. The combination with a fixed controller or gage and a positioning mechanism containing two oppositely-movable members or jaws whose closed position is determined by engagement with the fixed controller, of a shiftable member lying between and in the path traversed by said jaws when approaching or closing, and a centering and locking device engaging said shiftable member when brought to position by the jaws, for effecting final adjustment and locking the shiftable member while the jaws are receding therefrom, substantially as described.
- 20 64. The combination in a die or matrix centering mechanism such as described of the die-case, and its carrier and supporting-frame each provided with central guides intermediate its edge guides, as and for the purpose set forth.
- 25 65. A type-mold for use in a casting-machine comprising side blocks; a movable cross-blade; an adjustable mold-blade, the latter serving as an ejector; and an adjustable limiting-stop for the mold-blade, the whole mounted upon a detachable mold-frame.
- 30 66. In a type-mold for use in a casting-machine such as described, the combination with the side blocks supported on a mold-frame, and an adjustable mold-blade interposed between said side blocks and guided and supported wholly by the latter and the mold-frame, whereby distortion and binding of the mold-blade are prevented and the expansion and contraction of the parts of the mold are equalized.
- 35 67. In a type-casting mold for use in connection with a reciprocating nozzle, the combination therewith of a nozzle-plate provided with a thin-walled and bell-shaped seat for the nozzle, to prevent chilling the metal in the nozzle when the latter is seated in position to inject the molten metal into the mold; substantially as described.
- 40 68. In combination with the mold and nozzle, the nozzle-plate mounted upon the mold and provided with concave face and projecting bell nozzle-seat; substantially as described.
- 45 69. In a type-casting machine the combination with the detachable mold and its movable mold-blade for varying the dimensions of the mold-cavity and ejecting the type therefrom of the adjustable limiting-stop carried by
- the mold-frame and engaging the mold-blade; substantially as described.
- 70 70. In a mold-adjusting mechanism such as described, the combination with the mold-blade, its abutment-slide, the normal wedge and the justifying-wedge, of oppositely-reciprocating jaws engaging said wedges to set or adjust the latter; substantially as described.
- 75 71. The combination with the mold-blade abutment and an adjustable normal wedge for positioning the former, of a movable transfer-block interposed in the line of connection between the fixed bearing or abutment and the movable mold-blade abutment; substantially as described.
- 80 72. In a mold-adjusting mechanism the combination with the mold-blade abutment-slide, a main adjusting element, such as the normal wedge an adjustment-setting member, such as a transfer-block, and a plurality of supplemental adjusting elements, such as justifying-wedges, of controllable positioning mechanism for separately positioning each supplemental adjusting element and the main adjusting element; substantially as described.
- 85 73. The combination with a movable abutment-slide furnished with an adjustable contact for engagement with the mold-blade, of a normal wedge for determining the position of adjustment of the mold-blade, and a reciprocating wedge-shaped transfer-block co-operating with the normal wedge in setting the abutment-slide to the position indicated by the normal wedge; substantially as described.
- 90 74. In a mold-adjusting mechanism for type-casting machines, the combination with the mold-blade, actuating devices therefor and an adjustable intercepting abutment, of a transfer-block, a normal wedge, and actuating devices for reciprocating the transfer-block and adjusting the normal wedge; substantially as described.
- 95 75. In a mold-adjusting mechanism for type-machines, the combination with adjusting devices operating upon the mold-blade to determine its position in the mold when a cast is to be made, of a setting or adjusting mechanism including a transfer-block having a uniform range of motion, and a normal wedge having a variable motion of adjustment; substantially as described.
- 100 76. In a mold-blade-adjusting mechanism the combination with devices directly controlling the position of the mold-blade, such as an abutment-slide, of an adjusting or normal wedge, variable adjusting devices for moving said wedge to different positions of adjustment, a second wedge or transfer-block, and actuating devices for communicating uniform reciprocating movements to said second wedge; substantially as described.
- 105 77. In a mold-blade-adjusting mechanism the combination with the mold-blade abutment and the variably-adjustable normal wedge, of the transfer-block having a uniform reciprocating movement, and an adjustable

abutment fixed to the frame for defining one extreme of said reciprocating movement; substantially as described.

78. The combination with the abutment-slide for the mold-blade, a variably-adjustable normal wedge and a reciprocating transfer-block having a uniform degree of motion, of actuating devices for said transfer-block including yielding or elastic connections, and an adjusting-wedge against which the transfer-block contacts at the limit of its operative stroke in setting the abutment-slide to the position of adjustment determined by the normal wedge; substantially as described.

79. In a type-casting machine the combination with the movable mold-blade and its adjustable stop or abutment, of mold-blade-actuating mechanism, substantially as described, the latter comprising the head or slide carrying a cross-pin for engagement with the mold-blade, a rod connected to said head and provided with two springs, a headed sleeve engaging one of said springs and a loose collar the other, a sleeve interposed between the said loose collar and the headed sleeve, and an actuating-lever narrower than the interval between said collar and sleeve; substantially as described.

80. The combination with the transfer-blocks and a lock for holding either of said blocks at one extreme of its motion, or in inoperative position, of an actuating-lever and intermediate connections for transmitting the motion of said lever to either block; substantially as described.

81. The combination with the reciprocating transfer-blocks of the actuating-rods, the locking-rod and the yielding actuating devices intermediate said actuating-rods and the actuating-lever; substantially as described.

82. In combination with the transfer-blocks, their limiting-abutment and a lock for holding either block out of action, of an actuating mechanism comprising a spring-seated lever connected to one transfer-block, a second lever pivoted upon the first-named lever and connected to the other transfer-block and the driving mechanism or main actuating-lever connected to said second lever; substantially as described.

83. In a type-casting machine such as described, the combination with the mold and its movable mold-blade, of the abutment-slide located immediately in rear of the mold-blade, and the normal and justifying wedges located directly beneath said abutment-slide; substantially as described.

84. In a mold-adjusting mechanism such as described the combination with the normal and justifying wedges of the transfer-blocks loosely connected to their actuating-rods, to permit lateral displacement; substantially as described.

85. In a type-casting machine the combination with the mold, the horizontally and vertically movable die-case, and the actuating-lever controlling the vertical movements of

the die-case, of the mold-blade-adjusting devices including the adjustable normal wedge, the reciprocating transfer-block and the locking-bolt for said transfer-block connected to the die-case-actuating lever; substantially as described.

86. In a mold-adjusting mechanism the combination with the mold-blade, its abutment and actuating devices therefor, and the normal wedge, of the normal-wedge setting or adjusting mechanism including a primary controller or fixed gage; a primary positioning mechanism; a secondary controller or shiftable gage; and a secondary positioning mechanism, the latter operating upon the normal wedge to shift it to the position indicated by the primary controller; substantially as described.

87. In a mold-adjusting mechanism the combination with the mold-blade abutment and its movable support, of a longitudinally-adjustable normal wedge resting loosely in the interval between the mold-blade-abutment support and a fixed abutment or bearing, a reciprocating transfer-block intermediate said normal wedge and the fixed bearing, and actuating devices for retracting the transfer-block, during the adjustment of the normal wedge and bringing it into operating position after the normal wedge is adjusted, to set or position the mold-blade abutment; substantially as described.

88. In a mold-adjusting mechanism, the combination with the mold and its movable section or mold-blade, of a stepped or irregular normal wedge, for varying the position of said movable mold-section, and a controllable positioning mechanism for setting said stepped wedge in any one of a longitudinal series of uniformly-spaced positions; substantially as described.

89. In a mold-blade-adjusting mechanism the combination of the following elements, to wit; a mold-blade abutment; an adjustable normal wedge for positioning said abutment; and an automatic shifting or adjusting mechanism for carrying the normal wedge directly from one position of adjustment to another; substantially as described.

90. In a mold-blade-adjusting mechanism the combination of the following elements, to wit; a pair of oppositely-movable jaws adapted to be intercepted and closed at different points; a mold-blade-adjusting or normal wedge extending between the jaws and moved thereby; and a mold-blade abutment whose position is determined by the normal wedge and which serves in turn to fix the position of the mold-blade in the mold; substantially as described.

91. In a mold-adjusting mechanism the combination of the following elements, to wit; a mold-blade; a movable abutment; a normal wedge for positioning said abutment; and an automatic shifting or adjusting mechanism controlling the position of the normal wedge, comprising a pair of oppositely-movable jaws

engaging a portion of the normal wedge, and a gage intermediate the jaws upon which the latter are closed thus carrying the normal wedge to the position indicated by said gage; 5 substantially as described.

92. In a mold-blade-adjusting mechanism the combination of the following elements, to wit; a pair of oppositely-movable jaws adapted to be intercepted and closed at any point 10 in the line of their movement toward each other; a mold-blade-adjusting normal wedge extending between and in the path of motion of the jaws and moved thereby to adjusted position; a locking and final-adjusting device 15 for the normal wedge; and a mold-blade abutment whose position is determined by that of the normal wedge; substantially as described.

93. In a type-casting machine the combination with oppositely-movable jaws for positioning the die-case by engagement with translating devices connected therewith, of the normal wedge controlling the position of the mold-blade in the mold, said normal wedge or a part connected thereto projecting between 20 said jaws, so that the position of adjustment of the normal wedge will correspond with that of the die-case; substantially as described.

94. In a mold-adjusting mechanism such as described, the combination with the mold-blade and its abutment-slide, of a normal wedge provided with a discontinuous or stepped engaging surface; substantially as described.

95. In a mold-adjusting mechanism and in combination with the devices for positioning the mold-blade to produce mold-cavities of different dimensions, a sectional or stepped wedge for controlling, by its position, the various 25 positions of the mold-blade in the mold; substantially as described.

96. In a mold-adjusting mechanism the combination with the mold-blade and its abutment-slide, of a longitudinally - adjustable normal wedge, an abutment and a device engaging the normal wedge to withdraw it from the abutment during the adjustment of said wedge; substantially as described.

97. In a mold-adjusting mechanism such as described, the combination with the mold-blade and its positioning mechanism, of a stepped or irregular normal wedge; an abutment against which said wedge acts, a spring-seated holding - plate, for disengaging the wedge and holding it separated from its abutment during adjustment, and a reciprocating transfer block or wedge; substantially as described.

98. The combination to form a mold-blade-adjusting mechanism, of a normal wedge, a justifying-wedge and two transfer-blocks, one acting in conjunction with the normal wedge and the other with both the normal and justifying wedges; substantially as described.

99. The combination with a normal wedge movable to vary the position of the mold-blade in the mold, and a justifying-wedge

whose adjustments, added to those of the normal wedge, determine the position of the mold-blade when type of abnormal width are 70 to be produced, of two transfer-blocks, one for the normal wedge alone, and the other for the normal and justifying wedges together, actuating mechanism for reciprocating both transfer-blocks, and locking devices for locking or throwing out of action either of the transfer-blocks; substantially as described. 75

100. In a mold-blade and adjusting mechanism for varying the size of the mold-cavity, the combination of the following elements, to wit; a normal wedge for effecting normal adjustments of the mold-blade; a justifying-wedge for effecting abnormal adjustments of the mold-blade; a transfer block or wedge co-operating with the normal wedge; a second 80 transfer block or wedge co-operating with the normal and justifying wedges; actuating devices connected to both transfer-blocks; and a lock adapted to arrest one or the other of the transfer-blocks in retracted position leaving the other free to advance to operative position; substantially as described.

101. The combination with a laterally and longitudinally movable wedge, such as the justifying-wedge, of a positioning mechanism for effecting the longitudinal adjustments of the wedge, a lever or support engaging the wedge to shift it laterally into and out of engagement with the positioning mechanism, and controllable actuating devices for said 95 shifting lever or support.

102. In a wedge-adjusting mechanism such as described, the combination with a wedge supported to move laterally as well as longitudinally, and a positioning mechanism for 100 engaging and setting the wedge longitudinally, of shifting devices to move the wedge laterally into and out of engagement with the positioning mechanism; substantially as described.

103. In a mold-adjusting mechanism the combination with a controllable positioning mechanism provided with oppositely-movable jaws, of an adjusting device or mechanism comprising a wedge movable longitudinally for adjustment and laterally for engagement with the jaws of the positioning mechanism; substantially as described.

104. The combination with the oppositely-movable jaws of a controllable positioning mechanism, of an adjusting member, such as a justifying-wedge, normally disconnected from the positioning mechanism and provided with means for temporarily placing it under the control of the jaws of said positioning mechanism; substantially as described.

105. In an adjusting mechanism such as described the combination with a controllable positioning mechanism provided with oppositely-movable jaws, of a justifying-wedge 130 lying normally to one side of the plane of motion of said jaws but capable of being brought into engagement therewith, a shifting-lever engaging the wedge to carry it laterally into

or out of the path of the jaws, a trip pivoted upon the shifting-lever, and a stepped actuating-lever adapted to engage said trip to shift the wedge; substantially as described.

5 106. In an adjusting mechanism the combination with a controllable positioning mechanism provided with oppositely-movable jaws, of an adjusting member, such as the justifying-wedge, controllable mechanism for temporarily establishing an operative relation between said adjusting member and the jaws of the positioning mechanism, and a lock for holding said adjusting member in position when disengaged from its positioning mechanism; substantially as described.

10 107. In a mold-adjusting mechanism, the combination with the oppositely-movable jaws of the positioning mechanism, of a justifying-wedge, a locking-bar engaging detents on said wedge, a shiftable support or lever engaging the wedge, to temporarily disengage it from the locking-bar and carry it into the path of the positioning mechanism for effecting adjustment; substantially as described.

15 108. The combination to form a wedge setting or adjusting mechanism of the following elements, to wit; a reciprocating positioning mechanism provided with oppositely-movable jaws; a laterally and longitudinally movable wedge provided with a shoulder adapted to enter between and be engaged by the jaws of the positioning mechanism; a locking projection or bar engaging detents on the wedge when the latter is withdrawn from between the jaws; and a controllable mechanism for shifting the wedge laterally from the plane of the locking-bar into that of the jaws and vice versa; substantially as described.

20 109. The combination with a laterally and longitudinally movable adjusting-wedge, such as the justifying-wedge, and a controllable positioning mechanism for determining the position of adjustment of the wedge, of a detent engaging the wedge to hold it in adjusted position, a lever provided with jaws embracing the wedge and adapted to shift the latter from the detent into engagement with the positioning mechanism, an actuating-lever, and a trip intermediate said actuating-lever and shifting-lever; substantially as described.

25 110. The combination with a laterally and longitudinally movable wedge, such as the justifying-wedge, and a controllable positioning mechanism for effecting the longitudinal adjustments of the same, of a shifting-lever movable laterally of the wedge and engaging the latter to carry it into or out of connection with the positioning mechanism, an actuating-lever, a trip intermediate said actuating-lever and the shifting-lever, and a controllable trip-lever engaging the trip; substantially as described.

30 111. In a mold-adjusting mechanism such as described, the combination with the justifying-wedge and the positioning mechanism therefor, of the wedge-shifting lever pro-

vided with jaws between which said wedge is received and guided, a trip pivoted to said shifting-lever, a reciprocating actuating-lever for engaging the trip, a trip-lever operating upon said trip to shift it into engagement with the actuating-lever at predetermined intervals, and a piston operating said trip-lever; substantially as described.

35 112. The combination with oppositely-movable jaws and a gage or stop for determining their closed position, of a normal wedge provided with an engaging portion lying between and in the plane of movement of said jaws, a justifying-wedge provided with an engaging portion normally to one side of the plane of movement of the jaws but capable of being brought into said plane between the jaws, and two transfer-blocks brought into action dissimultaneously for rendering the adjustments of the normal wedge or of the normal and justifying wedges operative to effect the position of the mold-blade; substantially as described.

40 113. In a machine for automatically effecting the adjustments of a mold, to produce normal and justifying type, the combination of the following elements, to wit; a normal wedge and transfer-block for effecting normal adjustments or those corresponding with different widths of normal type; a justifying-wedge and transfer-block for effecting, in conjunction with the normal wedge, abnormal adjustments such as are required for justification; adjusting mechanism intermittently engaging the wedges to set and then release them; controllable devices for bringing the justifying-wedge temporarily under the influence of its adjusting mechanism; actuating devices for the transfer-blocks; and a lock for suspending the action of one or the other transfer-block; substantially as described.

45 114. In a mold-adjusting mechanism the combination with the mold and its mold-blade, and a movable abutment controlling the mold-blade when in casting position, of a wedge for adjusting the position of the mold-blade abutment, adjusting mechanism intermittently engaging said wedge to carry it to any position of adjustment and there leave it, a lock for holding the wedge in adjusted position, and a second wedge or transfer-block operating in conjunction with the first-named wedge to set the mold-blade abutment; substantially as described.

50 115. In a mold-adjusting mechanism the combination with the normal wedge and transfer-block of a plurality of justifying-wedges, adjusting devices for said justifying-wedges, and controllable devices for bringing the justifying-wedges temporarily and successively within the control of the adjusting devices; substantially as described.

55 116. In a mold-adjusting mechanism, the combination with the mold and its mold-blade, of a normal wedge, a justifying-wedge, an adjusting mechanism normally in operative relation with the normal wedge and in inoperative

relation with the justifying-wedge, controllable devices for placing the justifying-wedge temporarily within the control of said adjusting mechanism, and transfer-blocks for determining which of the adjusting factors—normal wedge alone or normal and justifying wedges together—shall operate upon the mold-blade; substantially as described.

117. In a mold-adjusting mechanism for type-casting machines the combination of the following elements, to wit; a plurality of adjusting elements, such as wedges; a plurality of setting devices, such as transfer-blocks, for rendering one or more of the adjusting elements operative upon the mold; and controllable positioning mechanism for setting said adjusting elements successively to predetermined positions of adjustment; substantially as described.

118. In a mold-adjusting mechanism for type-casting machines the combination of the following elements, to wit; a main adjusting element, such as the normal wedge; a supplemental adjusting element, such as a justification-wedge; controllable positioning mechanism for the main and supplemental adjusting elements; independent controllable devices for connecting the supplemental adjusting element with the controllable positioning mechanism; and two setting devices, such as the transfer-blocks, with controllable devices for bringing them alternately into action, to cause either the main or the main and supplemental adjusting elements to operate in conjunction with the movable member of the mold in fixing the width of the mold-cavity; substantially as described.

119. In a mold-adjusting mechanism for type-casting machines the combination of the following elements, to wit: a main adjusting member, such as the normal wedge, with controllable positioning mechanism for shifting the same to effect different degrees of adjustment; a supplemental adjusting member, such as a justifying-wedge, with controllable positioning mechanism for shifting it to different positions of adjustment; and a transfer mechanism, such as the transfer-blocks, for shifting the mold adjustment from the main to the main and supplemental adjusting members; substantially as described.

120. In a mold-adjusting mechanism for type-casting machines the combination with a controllable adjusting or positioning mechanism, including a pair of oppositely-movable jaws, and a main adjusting member, such as the normal wedge, of a supplemental adjusting member, such as a justifying-wedge, controllable devices for temporarily connecting said supplemental adjusting member with the adjusting or positioning mechanism, and controllable devices, such as the transfer-blocks, for establishing connection between the mold-blade and either the main or main and supplemental adjusting members; substantially as described.

121. In an adjusting mechanism the combi-

nation with the abutment-slide, the transfer-block, the normal wedge, and controllable positioning mechanism for setting the normal wedge, of the justifying-wedge and controllable devices for shifting the latter into and out of engagement with the positioning mechanism; substantially as described.

122. In a mold-adjusting mechanism for type-casting machines the combination with the normal wedge and the controllable positioning mechanism therefor, of a plurality of differently-tapered justifying-wedges, and controllable mechanism governing the connections between said positioning mechanism and the justifying-wedges to set the latter, whereby the adjustment effected is compounded of the separate adjustments of the several wedges as determined by their relative positions and tapers; substantially as described.

123. The combination with the reciprocatory transfer-blocks, each provided with a notched actuating-rod, of the locking-rod engaging said actuating-rods to lock one and release the other; substantially as described.

124. In a mold-adjusting mechanism for type-casting machines the combination with the normal and justifying wedges, the transfer-blocks, the mold-blade abutment-slide, and the controllable positioning mechanism with its oppositely-movable jaws for setting the wedges, of the locking-bolt for the normal wedge, the detent for the justifying-wedge, the shifting-lever for the justifying-wedge provided with a trip, and the actuating-lever operating both the normal-wedge lock and the shifting-lever for the justifying-wedge; substantially as described.

125. In a mold-adjusting mechanism such as described, the combination with a slide or movable member connected to the mold-blade, to determine the position of the latter in the mold, of the following elements, to wit; a bearing or shoulder upon said slide or movable member; two fixed abutments; a longitudinally-adjustable normal wedge engaging the bearing on the slide; an adjustable member, such as a justifying-wedge engaging one of the fixed abutments; two reciprocating transfer-blocks or setting-wedges, the one interposed between the normal wedge and a fixed abutment, and the other between the normal wedge and the adjustable member or justifying-wedge; and controllable mechanisms for setting the normal and justifying wedges and reciprocating the transfer-blocks; substantially as described.

126. In a type-casting and composing machine the combination of the following elements, to wit: a fixed mold; a horizontally and vertically movable die-case; a line-channel located to one side of and below the level of the mold; an ejector opposite the line-channel; and an angularly-reciprocating type-carrier provided with a type-receiving channel, a clamping member, and a type-sustaining gate or blade; whereby the type received from the mold are transported opposite the line-

- channel in position to be entered therein by the ejector; substantially as described.
127. In a type-casting machine provided with a horizontally-movable die-case and stationary mold, and in combination therewith, a horizontally and vertically reciprocating type-carrier for receiving the type as it is ejected from the mold; substantially as described.
128. In a type-casting machine such as described, the combination with a mold provided with a cross-blade, of a type-carrier connected to and reciprocating in unison with said cross-blade; substantially as described.
129. In a type-casting machine the combination with the mold and its cross-blade, the latter guided to reciprocate in a plane, of a type-carrier guided to reciprocate in a plane inclined to that of the cross-blade, and connected to the latter by a flexible joint or coupling; substantially as described.
130. The combination to form a type-carrier adapted to transport and deliver individual type, of a slide provided with a type channel or passage, a clamping-jaw movable transversely of said channel or passage, and a reciprocating and laterally-yielding type-sustaining blade projecting into said channel, substantially as described.
131. In a type-carrier such as described, the combination with the reciprocating slide provided with a transverse type passage or channel, of a spring-actuated clamping-jaw movable across said channel, a stop engaging said jaw to restrain the latter as the slide approaches the receiving-station, a laterally yielding type-supporting blade movable across the type-channel, and a lever mounted upon the slide and contacting with fixed abutments near opposite ends of its path to alternately project said type-supporting blade across the type-channel and withdraw it therefrom; substantially as described.
132. In a type-casting machine the combination with the mold, its movable wall or cross-blade and the ejector or mold-blade, of a type-carrier provided with a type-receiving channel or passage, a clamping-jaw movable transversely of said passage, a flexible type-sustaining blade extending across said passage, and actuating devices for retracting the clamping-jaw and advancing the type-sustaining blade as the carrier approaches the mold, for advancing the clamping-jaw to grasp the type as the carrier is retracted, and for retracting the type-sustaining blade as the carrier arrives in front of the ejector; substantially as described.
133. In a type-casting machine the combination with the mold, its cross-blade and mold-blade, the latter serving as an ejector, of the type-carrier, the latter comprising a reciprocating slide with transverse type-channel; a spring-actuated clamping-dog with limiting stop; a flexible type-sustaining blade extending through the clamping-dog and attached to a slide and a lever mounted upon the carrier-slide in position to engage fixed abutments and acting through a block and spring to advance and retract the type-supporting 70 blade; substantially as described.
134. The combination with the type-carrier provided with a movable clamping-jaw, of an ejector flanged along its upper and lower edges and provided with beveled shoulders in 75 advance of its type-engaging face, to insure the passage of the latter between the clamping walls or members; substantially as described.
135. In a type-carrier for casting-machines 80 the combination with the slide provided with a transverse type-channel and a spring-actuated clamping member, of a type-sustaining blade or gate, including a spring-blade 255 guided at its front or operating portion in 85 the clamping member and carried by a slide 251*, the latter operated through block 256, lever 258 and spring 257 to alternately advance said blade or gate into the type-channel and to withdraw it therefrom as the type-carrier slide is reciprocated between the receiving and delivering stations; substantially as described.
136. The combination to form a type-carrier such as described, of the following elements, to wit: a slide provided with a transverse type-channel; a clamping member or type-holder 251 guided to reciprocate laterally of the type-channel and projected therein by a spring; a gate or type-support 255 mounted upon a supporting-slide 251*, the latter furnished with shoulders or stops between which is received a block 256; and a lever 258 mounted upon the type-carrier in position to engage fixed stops on the frame, said lever 105 operating through elastic connections to reciprocate the type-supporting gate; substantially as described.
137. The combination with the reciprocating type-carrier provided with clamping-jaw 110 and a reciprocating and laterally yielding type-sustaining blade, of the ejector for discharging the type from the carrier, said ejector being held under spring tension against one of its guiding-surfaces and provided with inclines at its entering end engaging the carrier to facilitate the entrance of the ejector; substantially as described.
138. In a type-casting and composing machine such as described the combination with 120 the starting-lever of the galley mechanism, and the controllable member of the pump-actuating mechanism, of the shifting-lever for the justifying-wedge, and a shaft or connection engaged by said shifting-lever to actuate 125 the galley-starting lever and the controllable member of the pump-actuating mechanism; substantially as described.
139. In a galley mechanism such as described the combination of the following elements, to wit: an oscillatory reciprocating line-carrier pivotally attached to a reciprocating slide and provided with an arm movable between stops or shoulders on said slide, a

slide mounted in ways parallel with the first-named slide and engaging the arm of the line-carrier, and a reciprocating driving member movable between stops or bearings on said 5 second slide and engaging the latter; substantially as described.

140. In a galley mechanism such as described, and as a means for actuating the line-carrier, the combination with the latter, of a 10 slide or support mounted to reciprocate parallel with the line-channel, a line-carrier pivotally attached to said slide and provided with a laterally-projecting arm extending between limiting-stops on the slide, a second 15 slide, such as 283, engaging the arm on the line-carrier, a third slide, such as 287, provided with a pin riding in a longitudinal slot or opening in slide 283, and actuating devices including a double compression link or connection for reciprocating slide 287; substantially as described.

141. In a galley mechanism such as described the combination of the following elements, to wit: a line-carrier pivotally supported on a slide and provided with an arm extending between limiting-stops on said slide; a reciprocating slide, such as 283, engaging the line-carrier arm to oscillate the line-carrier and reciprocate it and its supporting-slide; a third slide or reciprocating member, such as 287, engaging slide 283; a laterally-movable bar; or line-transferrer; a line-supporting blade and resetting-slide carried by said movable bar; and a latch carried by 35 slide 287 for engagement with the resetting-slide of the line-supporting blade; substantially as described.

142. In a galley mechanism such as described and as a means for reciprocating the line-transferrer, the combination with the latter and its pivoted support or lever, of the cam, the actuating-lever and the compression-link intermediate said actuating-lever and the line-transferrer; substantially as described.

143. In a galley mechanism such as described, the combination with the driving-shaft, of a controllable connection between said shaft and the actuating devices of the galley mechanism, the same including a 50 ratchet-wheel, a spring-actuated pawl provided with an engaging shoulder and a pin, and an arresting and releasing lever provided with a shoulder extending normally in the path of the pawl and engaging the latter to withdraw it from the ratchet-wheel and arrest the motion of the actuating devices, and a latch carried by said lever and engaging the pawl in rear of the fixed shoulder on the lever, said latch being elevated by the pin to 55 permit the passage of the pawl; substantially as described.

144. In a galley mechanism such as described and in combination with the actuating mechanisms for the line-carrier, the line-transferrer and the vertically-movable blade, of the vertical driving-shaft, the cam loosely mounted thereon, the ratchet-wheel fast on

the shaft, the pawl pivoted upon the cam, and the locking and releasing lever provided with a fixed and a movable jaw or abutment, said 70 lever operating both as a starting and stopping device; substantially as described.

145. In a type-composing mechanism such as described, the combination with a reciprocating type-carrier provided with a transverse 75 type-receiving channel having fixed and moving clamping walls or members recessed or slotted horizontally at the delivery end in the plane of motion of said type-carrier, of a line-channel provided at its entering end with 80 type-sustaining devices, such as springs, the latter projecting partially within the line of motion of the type-carrier and entering the recessed or slotted portions of the clamping members, and an ejector reciprocating 85 through the type-carrier to force the type held between the clamping members thereof into the line-channel; substantially as described.

146. In combination with the reciprocating type-carrier and the ejector-blade, the line-channel furnished at its entering end with the type holding and sustaining springs 265 and 267; substantially as described.

147. In a controllable pump-actuating mechanism for type-casting machines such as described, the combination with the reciprocating driving member, the driven member and the interposed latch or detachable connection, of a power-actuated arm for operating said latch or detachable connection, a longitudinally-movable shaft upon which said arm is supported and moved into or out of engagement with the latch or detachable connection, said shaft being interposed between the controllable mechanism for setting the justifying 95 devices and the controllable starting devices of the galley mechanism and actuated by the former to suspend the pump action and start the galley mechanism when the justifying 100 adjustments are effected; substantially 105 as described.

148. In a type-casting machine the combination to form a controllable pump-actuating mechanism, of a reciprocating driving member, such as arm 223; a driven member, such 115 as arm 227, connected to the pump-actuating devices and provided with a latch, such as 226, for engagement with the driving member; a member, such as tripping-arm 230, reciprocating in a plane parallel with the latch; 120 and actuating devices for shifting said last-named member into and out of the path of the latch or a part connected therewith; substantially as described.

149. In a controllable pump-actuating mechanism for type-casting machines such as described, the combination with the driving and driven members and interposed connecting and disconnecting device, of a power-driven 125 reciprocating disconnecting member, such as arm 230, a longitudinally-movable shaft to which said arm is connected, a connection with the justifying adjusting mechanism for shifting said shaft, and a detent, such as the 130

5 spring-actuated plunger, connected to and moving in unison with the arm and engaging a seat on the frame, for maintaining the arm in adjusted position; substantially as described.

150. In a pump-controlling mechanism such as described the combination with a driving member or arm 223 connected to the pump-actuating lever or prime mover and provided 10 with an angular head, of a driven member or arm 227 connected to the pump-actuating devices; a latch carried by said driven member in position to engage the angular head of the driving member; a reciprocating member, 15 such as tripping-arm 230, movable longitudinally of its pivot to carry it into or out of the path of the latch; and a spring-seated pin or shoulder on the latch with which said tripping-arm engages when moved laterally; sub- 20 stantially as described.

151. In a controllable pump-actuating mechanism for a type-casting machine such as described, the combination with driving-arm 223, driven arm 227 with its latch 226 and 25 tripping-arm 230, of the shifting-lever for the justifying-wedge operating to shift the tripping-arm into engagement with the latch, and a detent for holding said tripping-arm in engagement with the latch after the withdrawal 30 of the justifying-wedge-shifting lever; substantially as described.

152. In a controllable actuating mechanism such as described, the combination with a driving member, a driven member, and a latch 35 or interlocking member, of a reciprocating arm 230, movable into and out of connection with said latch or interlocking member, a longitudinally-movable shaft upon which said arm is pivoted, and actuating devices for reciprocating the shaft to carry the latch-engaging arm into and out of operative connection with said latch; substantially as described.

153. In a pump-actuating mechanism such as described the combination of the following 45 elements, to wit; a pivotally-supported power-actuated driving-arm 223; a driven arm 227 sleeved upon the pivot of arm 223 and provided with an arm connected to the pump-operating devices; a latch 226 pivoted to one of said arms and detachably engaging the other arm; a shaft parallel with the axis of the driving and driven arms; a latch-operating arm 230 attached to a sleeve turning 50 loosely upon said shaft and held in position thereon between a shoulder and spring, so that the sleeve can be moved longitudinally of the shaft together with or independently of the latter, to bring its arm into the path of the latch; and controllable devices for moving 55 either the shaft and sleeve or the sleeve alone longitudinally of the shaft for causing the vibrating arm to engage the latch and thereby arrest the pump action; substantially as described.

154. In a pump-actuating mechanism such as described, as a means for transmitting mo-

tion from the actuating-lever to the connected piston and cylinder levers, the combination of sleeve 211 and its spring, shaft 212 passing 70 through said sleeve and connected to the actuating-lever through a compression-link and controllable power-transmitting devices, a cross-bar 208 secured to said shaft, and a pin passing through said cross-bar and a projection on sleeve 211 and provided with a stop or shoulder engaging said sleeve to limit its movement; substantially as described.

155. In a type-casting machine such as described, the combination with the metal-injecting devices and the mechanism controlling their motions toward and from the mold, of a vertical threaded shaft mounted in bearings on the main frame, and a supporting frame or base for the injecting devices pivoted upon said shaft and movable both longitudinally and laterally thereon; substantially as described.

156. In a metal-injecting apparatus such as described, the combination of the following 90 elements, to wit; a supporting base or frame attached to the main frame by a vertical pivot about which it can swing horizontally; the melting-pot, pump, nozzle and their elevating devices mounted upon said pivoted base or 95 frame; and a pump-lever pivotally connected to the actuating devices in line with the axis of the supporting-frame; substantially as described.

157. The combination with a reciprocating pump and nozzle, the spring-actuated mechanism for advancing and seating the nozzle and the connected opposing pump-actuating levers, of a reciprocating power-driven shaft carrying a bar or cross-head engaging both the 105 piston-lever and the spring-actuated mechanism, a sleeve surrounding the shaft and connected to the cylinder-lever, a spring for advancing said sleeve, and a stop for arresting the sleeve; substantially as described. 110

158. In a type-casting machine the combination with the mold, of a metal-injecting mechanism movable toward and from the mold and including a melting-pot, nozzle and pump, a parallel link support or guide therefor, and 115 actuating devices for elevating and depressing the connected receptacle, nozzle and pump, whereby regurgitation of the molten metal is prevented; substantially as described.

159. In a type-casting machine the combination with the mold and its nozzle-plate, of the nozzle, pump and melting-pot connected to move in unison, a parallel link support or guide, and a lifting-lever applied in line with the nozzle for elevating the metal-injecting 120 devices and seating the nozzle thereon; substantially as described.

160. In a metal-ejecting apparatus for type-casting machines the combination with the melting-pot, pump and nozzle, connected together and movable toward and from the mold, of a spring-actuated elevating and seating mechanism, and a pump-operating mechanism engaging the said elevating mechanism 130

to limit and control the action of its spring; substantially as described.

161. In a metal-ejecting apparatus for type-casting machines the combination with the pump, melting-pot and nozzle connected to move in unison and provided with a parallel link-guiding mechanism, of spring-actuated elevating devices and pump-actuating devices engaging said elevating devices to control the action of the spring in seating the nozzle; substantially as described.

162. In a pump-operating device for metal-injecting mechanisms the combination with the pump of opposing power-transmitting devices engaging the cylinder and piston respectively; substantially as described.

163. In a pump-operating mechanism such as described, and in combination with the cylinder and piston thereof, two opposing levers connected together and to the piston and cylinder respectively, and actuating devices engaging said levers to move them in relatively opposite directions, whereby the power for actuating the pump will operate equally upon the cylinder and piston but in opposite directions; substantially as described.

164. In a pump-operating mechanism the combination with the cylinder and the piston thereof, of two levers connected respectively to the piston and to the cylinder, a link connecting the two levers, and actuating devices engaging the levers to cause their separation or approach; substantially as described.

165. In a type-casting machine such as described the combination with a reciprocatory injecting mechanism, of pump - actuating mechanism consisting of two connected and oppositely-moving levers engaging the piston and the cylinder respectively; substantially as described.

166. In a type-casting machine the combination of a reciprocating spring-actuated injecting mechanism, of two parallel connected levers the one engaging the piston and the other the cylinder, and actuating devices engaging said levers to cause them to move in relatively opposite directions, whereby the unseating of the nozzle during the pump action is prevented; substantially as described.

167. The combination with a reciprocating injecting mechanism including a pump, and as a means for operating the latter, two opposing connected levers, the one operating upon the piston and the other upon the cylinder of the pump, an actuating device connected with each lever, and mechanism for reciprocating said actuating devices in unison with the injecting mechanism and for causing their separation when the cast is to be made; substantially as described.

168. In a type-casting machine the combination with the vertically-reciprocating injecting devices mounted upon a vertically and horizontally movable support or frame, of the pump-actuating levers connected together and to the piston and cylinder respectively, and vertically - reciprocating actuating de-

vices attached to the pump-actuating levers by swivel connections in alignment with the axis of the pivot by which the support of the injecting devices is attached to the main frame; substantially as described.

169. The combination with a reciprocating pump and its connected actuating-levers, the one operating upon the piston and the other upon the cylinder, of an actuating mechanism comprising a bar or cross-head 208, secured to a longitudinally-reciprocating power-shaft and connected to the piston-lever, a sleeve 211 surrounding said shaft and connected to the cylinder-lever, a spring engaging the sleeve and a stop for limiting the movement of the sleeve; substantially as described.

170. The combination with the movable melting-pot, nozzle and pump and the lever for actuating the same, of the spring-actuated rod engaging said lever, a lever 206 operating upon the rod in opposition to the spring, and the reciprocating shaft provided with a pump-actuating bar or cross-head, the latter engaging lever 206, substantially as described.

171. In an injecting mechanism such as described, the combination of a vertically-movable melting-pot, a pump seated in said pot and communicating with a nozzle, and a pump-actuating mechanism operating upon the cylinder and piston with a pressure equal in amount but opposite in direction; substantially as described.

172. The combination with the injecting devices, including melting-pot, pump and nozzle, and the support therefor, of the two parallel shafts mounted upon the support and provided with arms to which the injecting devices are pivoted, connections between said shafts to cause them to turn in unison, and a lifting-lever engaging the injecting devices, to reciprocate the latter; substantially as described.

173. In a metal-injecting mechanism such as described the melting-pot, nozzle and connecting-conduit, provided with a combustion-chamber below the melting-pot, and a flue or passage for the products of combustion extending from the combustion - chamber beneath the conduit, thence vertically to a point near the nozzle, downwardly and rearwardly above the conduit and laterally to the escape-pipe.

174. In a paper-feeding mechanism the combination with the ratchet-wheel, of a locking-pawl guided to move radially of the ratchet-wheel and provided with a slot or recess substantially concentric with said wheel, and a feeding-pawl mounted upon a support movable concentrically with the wheel and provided with two operating-arms extending on opposite sides of its pivotal connection with its support, one of said arms engaging the ratchet-wheel and the other riding in the slot or recess of the locking-pawl; substantially as described.

175. In a feeding mechanism the combina-

tion with the ratchet-wheel, of the slotted locking-pawl, a pivoted actuating-pawl extending on opposite sides of its pivot for engagement with the ratchet-wheel and the locking-pawl respectively, a movable support for said actuating-pawl provided with limiting-stops, and driving mechanism connected to the actuating-pawl to oscillate and reciprocate the latter; substantially as described.

176. The combination of the ratchet-wheel, pivoted locking-pawl, annular supporting-plate, and a feeding-pawl pivoted upon the supporting-plate and provided with three arms one engaging the ratchet-wheel, another the locking-pawl and the third the actuating devices, the latter including a compression-link or equivalent yielding connection; substantially as described.

177. The combination with the ratchet-wheel, and locking-pawl, of an oscillatory reciprocating actuating-pawl engaging the locking-pawl and the ratchet-wheel, actuating mechanism engaging the actuating-pawl and including a compression-link, and a controllable stop or lever for holding the locking-

pawl in fixed relation to the ratchet-wheel, thereby suspending the feed motion; substantially as described.

178. In a paper-feeding mechanism such as described the combination with mechanism 30 for intermittently advancing the strip, of a stationary cross-bar containing air-ports, an air-bar supported upon pivoted arms, a lever connected to the driving mechanism, a rod connected to the air-bar and passing through 35 the lever and a spring interposed between said air-bar and lever; substantially as described.

179. The combination in a paper-feed-operating mechanism and with the actuating-lever thereof, the link provided with a slotted head engaging a pin on the actuating-lever, and a swinging block interposed between said pin and slotted head and provided with a detent; substantially as described.
